ABSTRACT OF THE DISCLOSURE

A textile spinning frame including apparatus for automatically doffing and donning bobbins and, if desired, for rejoining breaks occurring in a strand of yarn. A carriage passes the numerous spinning positions on the frame and automatically delays its travel to service any spinning position requiring attention.

INTRODUCTION

This invention relates to the field of textile spinning frames for processing staple fibers and is concerned more particularly with an automatic tender for such frames.

Although modern spinning frames have been developed to a high level of efficiency, they are not yet capable of running without interruption between bobbin changes. Thus, studies have been shown that an average of 20-30 ends down per 1,000 hours of spindle operation can be expected. While this number is relatively small, it is sufficient to require the presence of an operator to perform the delicate operation of piecing up the down end to restore the spindle to production. The need exists, therefore, for a mechanism adapted to carry out this operation automatically and, incidentally, to doff such bobbins as are fully wound, don empty bobbins and initiate spinning on the new bobbins.

One object of the present invention is to provide an apparatus for travelling cyclically along one or more spinning frames and returning to production those spindles which are inoperative because of a broken end.

Another object of the present invention is to provide an apparatus capable of doffing a wound bobbin from the spindle of a spinning frame.

Another object of the present invention is to provide an apparatus capable of placing an empty bobbin on a spindle of a spinning frame and initiating winding thereon.

Another object of the present invention is to provide an apparatus capable of randomly doffing a wound bobbin from a spinning frame while avoiding the necessity of halting the operation of the remaining spinning stations of the frame.

A further object of the present invention is to provide an apparatus capable of automatically reuniting the outer yarn end on a take-up package with its companion end flowing from a roving supply.

Still a further object of the present invention is to provide apparatus capable of rejoining the outer end of yarn of a take-up package on a spinning frame with its companion supply end at a spinning station of a textile frame, and automatically reinstituting the normal spinning and winding cycle thereof.

A further object of the present invention is to provide apparatus capable of moving a free strand end along a predetermined path while imparting twist thereto.

Yet, another object of the present invention is to provide apparatus capable of automatically threading a strand through the traveller of a spinning frame.

Still, a further object of the present invention is to provide apparatus capable of returning to production those spindles of a spinning frame which are inoperative because of broken ends wherein the supply end is auto-

2

matically connected to the take-up means while being twisted.

An additional object of the present invention is to provide apparatus for repairing a break occurring in strandular material being processed on a textile machine, and including means for sensing said break and for sensing the failure of such repair procedure.

Other more specific objects and advantages will be apparent from the following detailed description when read in conjunction with the appended drawings in which:

FIG. 1 (Sheet 1) is a front elevation of a section of a spinning frame equipped with one embodiment of the apparatus of this invention, only enough of the frame components being shown as to convey the manner in which the invention is associated therewith, certain parts being cut away or omitted for clarity;

FIG. 2 (Sheet 2) is a transverse cross-section of the apparatus of FIG. 1 taken substantially along line 2—2 of FIG. 1 with some parts omitted or cut away, again for sake of clarity;

FIG. 3 (Sheet 3) is an enlarged detail view of the sub-carriage assembly shown in side elevation somewhat similar to FIG. 2.

FIG. 4 (Sheet 4) is a perspective view of the carrier registering mechanism of the invention, the carriage lock actuating mechanism being omitted for lack of space;

FIG. 5 (Sheet 4) is a front elevation of the mechanism of FIG. 4 including the actuating lever and solenoid;

FIG. 18 (Sheet 7) is a perspective view of a fragment of the mechanism of FIG. 17 taken from a different direction and showing such mechanism as it first makes contact with the yarn being threaded;

FIG. 19 (Sheet 7) is an augmented view similar to FIG. 18 showing an intermediate stage of the mechanism;

FIG. 20 (Sheet 4) is a plan view looking down on the mechanism of FIGS. 18 and 19 showing the final operative stage thereof with the traveller engaged on the yarn;

FIG. 21 (Sheet 3) is a perspective view similar to FIG.

17, but reduced in size, showing an intermediate position of a part of the bobbin threading mechanism;

FIG. 22 (Sheet 3) is a greatly enlarged detail view of the portion of the bobbin threading mechanism visible in FIG. 21 omitting its driving components;

FIG. 23 (Sheet 3) is a view somewhat similar to FIG. 19 but taken from a different direction, showing the operative position of the bobbin threading mechanism in relationship to the final operative position of the traveller threading mechanism;

FIG. 24 (Sheet 4) is an enlarged detail view showing the full bobbin cut-off mechanism of the invention;

FIG. 25 (Sheet 4) is a diagrammatic view representing the traverse motion for the ring rail in accordance with the invention;

FIG. 26 (Sheet 8) is a front elevation of a part of a spinning frame equipped with an embodiment of the invention having a modified power supply, only enough parts being shown as to illustrate the extent of the modification;

FIG. 27 (Sheet 8) is a detail view taken in transverse cross-section generally along line 27—27 of FIG. 26;

FIG. 28 (Sheet 9) is a perspective view, greatly enlarged, of a modified yarn-sensing mechanism, showing the same in operative position in the absence of yarn, the housing and certain other parts being cut away;

FIG. 29 (Sheet 9) is a detail view of the thread guide element and support used in the modified embodiment of FIG. 28 showing the guide maintained in inoperative position by the presence of yarn;

FIG. 30 (Sheet 10) is a diagram of the control circuit of the apparatus of the invention including both electrical and pneumatically actuated components in schematic form;

FIG. 31 (Sheet 11) is a timing diagram of the control cycle of the invention, showing the chronological relationship of some of the more important operations carried out by the invention.

FIG. 32 (Sheet 6) is an enlarged perspective view of the mechanism for effecting threading of the yarn on the bobbin;

FIG. 33 (Sheet 12) is a side elevational view of an alternate embodiment of the apparatus of the instant invention shown in operative relationship with a section of a spinning frame, only so much of the spinning frame being shown as to convey the manner in which the invention is associated therewith, certain parts being cut away or omitted for clarity;

FIG. 34 (Sheet 13) is a perspective view of the apparatus of FIG. 33, with certain parts in changed positions;

FIG. 35 (Sheet 14) is an enlarged detail view of the mechanism of FIGS. 33 and 34 for transporting the yarn end from the take-up package to the knotter, and the mechanism for conveying the spun roving end to the knotter, the yarn and spun roving being shown residing in the knotter;

FIG. 36 (Sheet 15) is a further perspective view of the yarn transporting mechanism of FIG. 35, the suction nozzle thereof being illustrated preparatory to its descent to position the yarn adjacent the ring rail for threading through its traveller;

FIG. 37 (Sheet 16) is a cross-sectional view of the bobbin transporting means;

FIG. 38 (Sheet 16) is an enlarged detail view of the mechanisms of FIG. 33 for retrieving the yarn end from the package, and the knotter and knotter supporting members, both the yarn retrieving mechanism and the knotter being illustrated in their respective inactive positions;

FIG. 39 (Sheet 16) is a view similar to FIG. 38, the knotter being omitted, and the yarn retrieving mechanism shown in its operative location to draw the outer yarn end off the wound package;

FIG. 40 (Sheet 16) is an enlarged detail elevational view of the brush and capstan for retrieving the yarn end

from the package, these elements being illustrated in the position of FIG. 38;

FIGS. 41-44 (Sheet 17) are views illustrating the steps in threading the yarn from the package through the traveller;

FIG. 45 (Sheet 17) is a perspective view of the traveller threading mechanism, the mechanism being depicted in the position of FIG. 44;

FIG. 46 (Sheet 15) is a plan view of the thread guide removal mechanism of the apparatus of FIG. 33;

FIG. 47 (Sheet 15) is a detail side elevational view illustrating one of the yarn guides rocked to its inoperative position by the removal mechanism therefor;

FIG. 48 (Sheet 15) is a detail plan view of the yarn sensing means of the apparatus of FIG. 33, and the mounting means therefor;

FIG. 49 (Sheet 18) is a block diagram schematically illustrating the control circuit for the apparatus of FIG. 33; and

FIG. 50 (Sheet 19) is a timing diagram of the control cycle of the embodiment of FIG. 33, showing the chronological relationship of some of the more important operations carried out by this alternate embodiment.

GENERAL DESCRIPTION

In general, the present machine comprises a main carriage adapted to move horizontally in a cycle along a path adjacent the side or sides of a spinning frame. This horizontal movement can be in any convenient manner and can relate to one or a plurality of spinning frames. For example movement of the carriage can be in a single direction and the carriage arranged to go around one, or a plurality of longitudinally aligned spinning frames so that it is operatively associated with first one side and then another. Alternatively, the carriage can reciprocate horizontally back and forth along one face of one or a plurality of longitudinally aligned spinning machines. On the main carriage is a sub-carriage mounted for independent vertical movement, such sub-carriage having rolling or sliding engagement with the ring rail of the frame to reciprocate bodily in a vertical direction with the ring rail while travelling with the main carriage. A sensing device detects the absence of yarn at any spinning position and initiates a cycle to restore that position to operative condition. In response to the sensing device, the carriage brings itself to a stop in transverse registration with the position to be serviced, halts the rotation of the bobbin, and ultimately dons an empty bobbin on the spindle. The fixtures above the spindle are retracted to clear the path thereto and the drafted roving issuing from the delivery set of draft rolls is snared, preferably by a vortex suction nozzle, and drawn down along a path extending adjacent the outside of the ring rail to a point below that rail and held in such position. Next, the strand is displaced from that path into partial wrapping contact with the ring outer surface and the traveller for the ring hooked over the strand. Then, the strand is released from the first snaring means and re-snared from the inside of the ring rail and drawn downwardly to a point adjacent the spindle base.

Rotation of the empty bobbin is started and the strand is caught on the bobbin and wound thereon. While the carriage remains in position, the spinning position is tested for running yarn and if the test is positive, the carriage is returned to its patrol. If the test is negative, indicating a failure, the position is rendered non-responsive to the sensing device, and the machine operator is signaled and patrolling of the carriage is resumed. If a predetermined number of failures occur in succession, the carriage shuts itself down and signals the operator. A supply of empty bobbins is provided on the carriage and when that supply is exhausted, the carriage returns to one end of the frame for a new supply.

The sensing device also detects the presence of a fully wound bobbin and stops the carriage as described above. The fully wound bobbin is thereupon doffed and replaced

with an empty bobbin, and the twisting and winding cycle automatically reinitiated to take-up the twisted material on the fresh bobbin.

DETAILED DESCRIPTION

Conventional spinning frame

The construction and operation of the conventional spinning frame which provides the context in which the improvement of the present invention occurs is well known to those skilled in the art and requires no detailed description here. Only enough of the parts of the conventional frame appear in the drawings, especially FIGS. 1 and 2, as is necessary to convey the manner in which the present invention is associated with the frame. Thus, there can be seen in the figures just named the legs 22 which carry the supporting components of the frame at spaced intervals along its length and are braced horizontally by means of crossbars such as indicated fragmentarily at 24 and at the frame ends by end strands 26, a fragment of which is seen in FIG. 2.

At the top of the frame is a roving bobbin creel 23 which supports a supply bobbin of the roving to be spun in any suitable way, as by means, for example, of a bracket 30 engaging and enlodged in a roving bobbin R. The roving Y extends from bobbin R downwardly to the drafting section of the frame which is supported on the draft roll rail 32. This section includes suitable roll stands 34 for supporting in opposed relation a plurality of pairs of drafting rolls 36, 37 and 38, the respective pairs being driven at a predetermined ratio increasing from rear to front so as to progressively elongate the roving directed thereto via a trumpet guide 39. From the nip of the front or delivery pair of the draft rolls 38, the now attenuated strand passes through a thread board including a guide eye 40 mounted on the front of the roll rail 32 on an articulated bracket 42 to permit the forward portion of the bracket and the guide eye to be flipped up to an out of the way position. Traditionally, a pig tail guide is employed as the guide eye 40; however, for purposes of this invention, a self-threading guide eye is preferably substituted as will be described more fully later.

Arranged between the draft roll rail 32 and the frame legs 22 is the spindle rail 44 on which are journaled a plurality of spindles 46 for holding the take-up bobbins B on which the spun yarn is wound to form the take-up package P. In FIG. 2, the forward spindle is shown in the interior position after removal of the wound bobbin but before the addition of an empty bobbin. Just above the journal of rail 44, each of the spindles 46 is provided with a whorl 49 which is engaged by a flexible driving belt (not shown) in order to rotate the spindle and the bobbin.

In order to guide the strand to the take-up bobbin, each of the spindles 46 is encircled by a ring 50 carried on a ring rail 52 extending lengthwise of the frame parallel to spindle rail 44. A traveller 54 (see FIGS. 1 and 17) rides around the upper flange of the ring 50 in engagement with the yarn to hold the yarn clear of the bobbin periphery. Distribution of the yarn along the length of the take-up bobbin 48 to form a satisfactory package is effected by reciprocating the rail vertically via lift rods provided at spaced points along its length, seen only fragmentarily at 58 in FIG. 2. The extent of reciprocation of the lift rods 58, and thus of the ring rail, is controlled by the ring rail motion indicated at 60. Journals for the lift rods 58 are provided in the spindle rail 44 as well as in a bottom rail 62, the last of the principal load-bearing components of the frame as far as this invention is concerned.

Various motions have been devised for the ring rail of spinning frames, down twisters and the like to provide for the production of yarn packages of particular configurations. As the capability of replacing a bobbin randomly at any time during the spinning cycle is preferred in the practice of the invention, the ring rail should have a constant, repetitive motion, one satisfactory rail traverse motion being shown in FIG. 25. Using the latter motion, the

bobbin should have an enlarged tapering base as can be seen in FIG. 2, to produce a cylindrical yarn package adapted for over-end unwinding.

At the present time, virtually all spinning frames are provided with a waste collection system typically sold under the trade name "Pneumafl." This system includes a suction pipe 64 arranged as closely as possible to the nip of the delivery pair of drafting rolls 38, pipe 64 being slotted along its length at 66 in the correspondence with the stands of rolls as is best seen in FIG. 2. Pipe 64 is communicated at each position with a suction manifold 68 through a rearwardly extending duct 69. In the event the attenuated strand y breaks after emerging from the nip of the delivery pair of rolls 38, the broken end is attracted by the suction to the slot 66 into the tube 64 and thence to the manifold 68 and ultimately through connecting conduits to a central waste collection point where the waste can be accumulated for reuse or disposal, as desired. By virtue of such a suction system, the build-up of so-called roll laps is minimized.

Up to this point, the description has been confined to the conventional spinning frame which, except as serving as a context for the present invention, forms no part of it. From this point on, the discussion will be concerned 25 more particularly with the details of the invention.

STRUCTURE OF THE INVENTION

Main embodiment

A. MAIN CARRIAGE AND CARRIAGE DRIVE MECHANISM

All of the operative components which make up the present invention are carried on a travelling main carriage, generally designated C in the drawings, which includes a floor or deck 70 together with corner posts 72 rigidly upstanding from the several corners thereof. To provide a track on which the carriage C may travel lengthwise of the frame in close proximity to the row of spinning positions, the bottom rail 62 of the frame has fixedly attached to the front side thereof a massive load rail 74, which, for purposes of this embodiment, takes the form of a C-shaped channel (FIG. 2) and the spindle rail 44 of the frame is provided with a similarly fixed guide rail 76. Rail 74 bears substantially the full weight of the carriage C by means of a plurality of rollers 78 journaled on horizontal shafts projecting inwardly of the rear corners of deck 70, while proper vertical alignment is maintained by guide rail 76 through engagement of its lower edge between the flanges of several guide rollers 80 journaled on stub shafts 82 projecting rearwardly from the upper end of a rear panel 83 rigidly upstanding from the deck. Together, the rails 74 and 76 provide a stable support for the carriage while permitting its free longitudinal movement along the front side of the frame.

In the embodiment of FIGS. 1 and 2, the motive power necessary for driving the carriage and carrying out various functions to be hereinafter explained is supplied in the form of electric current. Thus, a bus bar 84 is arranged within the interior of the channel of the load rail 74, being shielded against contact with the channel by appropriate insulation, and contact is made with bus bar 84 by a sliding shoe 86 moving with the carriage C and connected with a suitable distribution board (not shown) from which the current may be tapped as desired. A number of the operations performed by the apparatus of the invention are carried out by pneumatic means, which require, of course, some supply of compressed air. To this end, there is suspended from beneath the floor 70 of carriage C, an electrical motor 90 which drives an air compressor 92 discharging into a compressed air accumulator 94. Automatic regulating means (not shown) are provided to maintain a given pressure in accumulator 94, starting the motor 90 when the pressure drops and shutting off the motor when the pressure has been re-attained. Neither the electrical leads nor pneumatic lines have been

shown in the drawings as their presence would obscure mechanical or structural features having greater significance to a proper understanding of the operation of the invention. Rather, the entire electrical and pneumatic control system is set forth in a single coherent diagram, FIG. 30.

Reference has already been made to the fact that the carriage travels along the front side of the frame and some suitable driving means must naturally be provided to drive the carriage. In the illustrated embodiment, the driving means takes the form of an air motor 96 drawing compressed air from accumulator 94. The output shaft of air motor 96 drives a pulley 100 through a timing belt 102, the pulley 100 being fixed to the shaft of one of the load rollers 78 of the carriage C. Preferably, this roller is constructed of hard resilient material having a high coefficient of friction, such as hard rubber, and the journal for the load roller shaft is adjustable vertically by means not shown to permit the load roller to be urged against the top surface of load rail 74 under any desired degree of compressional loading. These two measures, combined with the use of a timing belt coupling the air motor and the drive pulley 100, serve to give a positive reliable driving connection between the carriage and the track. However, since the air motor by its very nature is capable of "stalling" for an indefinite period without damage, the use of such a motor provides a clutching action necessary to prevent damage to the carriage in the event its passage is obstructed.

The apparatus of the invention can travel continuously around a given spinning frame in a single direction, in which case air motor 96 is connected directly to the accumulator 94. However, it is preferred for the carriage to travel to and fro along one side of a given spinning frame or a series of such frames arranged in closely spaced longitudinal alignment such as to share a common track. For this preferred arrangement, the air motor must be capable of driving in either direction along the track; this capability is obtained by passing the air flow to the air motor through a solenoid-actuated 4-way drive control valve 104. Valve 104 supplies the compressed air to one side of the air motor to rotate the same in one direction when the solenoid is energized and to the other side of the motor to rotate the same in an opposite direction when the solenoid is de-energized and its armature is biased to inoperative position. The air motor is preferably able to drive the carriage at two speeds, a normal patrolling speed of about one foot/second and a low speed of about one-half normal speed, to facilitate precise carriage registration. The exhaust from the air motor therefor passes through a throttle valve 106 which is also solenoid actuated. When the solenoid of the valve 106 is energized, it partially closes, increasing the back pressure in the air motor and retarding its rotation to the degree that the air exhaust is throttled. A suitable solenoid operated 4-way control valve is model No. BV4-0602-B manufactured by Aero Modernair of Angol, Ind.

As the carriage C in the preferred arrangement shown in the drawings travels to and fro along one side of the spinning frame, its direction of travel must be automatically reversed when it reaches each end of the frame. For this purpose, one end of the carriage is equipped with a reversing switch indicated at 108 at the lower left portion of FIG. 2. The armature of the switch projects to a convenient point for abutment with limit stops 109 (FIG. 1) provided at the appropriate point adjacent the end of the bottom rail 62 of the frame. It is understood, of course, that if the switch is located asymmetrically with respect to the carriage, the limit stop at one end of the frame must be located a correspondingly greater distance from the end stand of the frame than at the other end. Switch 108 is interposed in the electrical circuit energizing the solenoid of the solenoid-operated 4-way drive control valve 104 so that when the switch armature is contacted by the limit stop at either frame end, the solenoid is either energized

or de-energized, as is necessary to reverse the driving direction of air motor 96.

B. VERTICALLY MOVABLE SUB-CARRIAGE

While certain of the functions required to be carried out in accordance with the present invention can be performed by components supported on the same horizontal plane provided by the deck of the carriage C, other functions have to be performed in relation to the ring rail of the spinning frame which, as has already been indicated, has a controlled pattern of reciprocating movement throughout the spinning cycle. To carry the components adapted to achieve these functions, the carriage is equipped with a vertically movable sub-carriage I, best seen in FIG. 1, and in particular, FIG. 3. Sub-carriage I includes a platform 110 which is guided for vertical movement by means of a pair of upstanding guide posts 112 (FIG. 3) fastened at their lower ends to the carriage deck 70 and passing through openings for that purpose in the platform 110. To counterbalance the weight of the sub-carriage and the components carried thereon, a cable 116 is connected at one end to the platform 110 as at 118 and at the other end to a tension spring 120 secured to the deck 70 and preferably protected by a housing 122. Between its ends, cable 116 passes around pulley 124 journaled on the upper end of guidepost 112. The tension in spring 120 is so selected as to support the greater part of the weight of the sub-carriage and its supported components so that the platform can be positioned vertically through a limited range of reciprocation corresponding to the traverse of the ring rail by the application of a relatively small amount of additional force thereto. Such additional force, in the illustrative embodiment, is supplied by means of a sub-carriage positioning rail 126 extending in slightly spaced relationship forwardly of the front side of ring rail 52 and firmly secured thereto for movement therewith. Rail 126 is engaged on both its top and bottom surfaces by means of flanged guide rollers 128, 130, which are journaled, respectively, in upper and lower brackets 134 fixed to the inner edge of platform 110. It follows, therefore, that as ring rail 52 traverses the length of the bobbin, such movement is imparted directly to the sub-carriage I.

C. CARRIAGE BRAKING AND REGISTERING MECHANISM

When a spinning position on the frame is found to require attention, as indicated by the operation of a yarn sensing device to be described later, the carriage is brought to a halt at a point in proper longitudinal alignment with that position. The spinning frame preferably includes a registration guide for each position and any of a variety of ways could be used to provide such an indication. As shown in the drawings, especially FIGS. 4 and 5, this can take the form of registration notches 129 cut into the top edge of the carriage guide rail 76 and a forwardly projecting flange present for this purpose at the upper end of carriage guide rail 76. A position registration switch 132 is mounted on the inside of carriage C and its armature terminates in a forward roller 133 following the contour of the front edge of the rail flange. When the follower drops into one of the notches 129, the contacts of switch 132 close, giving an indication that the carriage is in proper alignment with a spindle position. It is not necessary that the notch entered by the switch correspond with the particular position at which the carriage is to be halted and if spatial considerations require, any notch in reasonable proximity to the position to be serviced can be selected. In the case of the illustrative embodiment, for example, the notch providing the registration indication is twice removed from the position being attended.

As the inertia of the carriage is relatively high and some of the components carried thereon are of a rather delicate nature, it is advantageous in certain instances to bring the carriage to a halt at a more gradual rate. One way to accomplish this is to use the conjunction of an

indication of the absence of yarn, as provided by the yarn sensing device, and the indication of arrival of the carriage at the corresponding position, as provided by the position registration switch 132, to shift the drive control valve 104 determining the direction of rotation of the carriage driving air motor 96 and, hence, the direction of movement of the carriage and thereby reverse the direction of rotation of the air motor. Reversal of the air motor applies a braking resistance to the driving pulley 78, decelerating the forward progress of the carriage without damaging the motor by virtue of its inherent "clutching" action. In addition to shifting the drive control valve 104, the conjunction of the two indications is also used to actuate the solenoid of the throttling valve 106 so that the speed of the air motor is reduced. By the time the carriage has dissipated its momentum, it has overrun the location of the position requiring attention. At the same time, however, the air motor has reversed its driving direction to back up the carriage and does so until such backward motion is stopped by engagement of a carriage registration lock next to be described, with special reference to FIGS. 2, 4, and 5.

A supporting panel 140 (FIG. 1) is a part of the carriage frame and is suitably mounted as between the inside right corner post 72 and the inner guide post 112, platform 110 being appropriately notched at its right corner to provide clearance for the panel. Fulcrumed on this panel is a carriage lock lever 142 extending generally horizontally. At approximately its mid-point, lever 142 is pivotally connected to the armature of a solenoid 144 held in a bracket 146 on panel 140. At its extreme left end, lever 142 is pivoted to a locking rod 148 which is guided in a vertical direction by means of a guide block 150 secured to the inner guidepost 112 below the limits of travel of the sub-carriage I. The lower end of locking rod 148 is tapered, as indicated at 153, for engagement with registration notches 129 in the carriage guide rail 76.

With the solenoid 144 deactivated, locking pin 148 is held out of engagement with the carriage guide rail. Upon the conjunction of the two indications mentioned above, the solenoid 144 is energized through electrical components, to be described in connection with the over-all circuitry of the apparatus, forcing locking rod 148 downwardly into contact with the top of the flange of rail 76. The reaction of solenoid 144 is sufficiently slow as to allow the carriage to overrun the notch to be ultimately engaged, the tapered end 153 of the locking pin sliding on the surface of the rail. However, the solenoid remains energized and, as the carriage is backed up, tapered end 153 wedges in one of the notches 129. In this way the carriage is held firmly against any further longitudinal movement until solenoid 144 is de-energized, the air motor 96 stalled all the while. As in the case of the position registration switch 132, the locking pin need not engage the notch at the particular position requiring attention, but can work in conjunction with any reasonably proximate notch, such as the next adjacent notch as in the case of the illustrative embodiment.

D. DEFECTIVE POSITION SHUNT MECHANISM

If the apparatus of the invention has gone through its rethreading cycle at one position without success due to some radical difficulty beyond the capacity of the apparatus to correct, it is pointless for the carriage to stop again at the same position upon its next trip until the difficulty is obviated by direct attention from the machine operator. Accordingly, the present apparatus includes means for shunting the carriage registration mechanism around those positions in temporarily irreparable condition and as the mechanical features of this shunting arrangement are associated with the spindle registration mechanism, they are most conveniently described at this point. On the front face of carriage guide rail 76 below the flange bearing the registration notches 129 are provided shunt plates 156, one plate for each notch. The

plates 156 are slotted longitudinally, as at 158, and are maintained in sliding contact against the rail face by means of spaced bolts 159. An operating tab 160 projects outwardly from one end of the plate so that each plate can be moved from a normal inoperative position entirely to one side of a registration notch 129 to a shunt position extending beneath and across such notch. The other end is beveled as at 161. The thickness of plates 156 is the same as that of the rail flange so that the plate outer surface will be substantially coplanar with the outer surface of the flange and the follower roller 133 of the registration switch 131 is of such a length as to extend below the rail flange. So long as shunt plates 156 are in inoperative position, the armature follower is free to move into the registration notches 129. However, when a shunt or cover plate is moved beneath a notch, the armature follower 133 will roll along its surface and will be prevented from dropping into the notch.

The means for setting the shunt plates in shunt position may take the form of a solenoid 162 mounted on the inside of guide post 112 below locking pin guide block 150, the armature of the solenoid carrying an operating blade 164 having an inclined cam surface 166 adapted to engage the plate operating tab 160 and cam the tab and plate into shunt position. As appears in the drawings, FIGS. 4 and 5, tab 160 is offset from the top edge of the plate in order to avoid interference with the armature follower 133. The machine attendant, after correcting the radical difficulty, manually resets the shunt plates to normal inoperative position.

E. SPINDLE BRAKING MECHANISM

According to the conventional practice of the art, textile spinning frames are operated on an entire frame basis, which is to say, that an entire frame is started and stopped at the same time, no provision being made for starting and stopping individual spindles. As it is presumed that the frame with which the automatic tender of this invention is associated for purposes of illustration is of a conventional type, it follows that the spindle at the position requiring attention continues to rotate without regard to any inruption in the flow of yarn thereto. This is not to imply that the invention would have no utility with spinning frames of other types as the successful practice of the invention in no way depends upon whether the spindle continues to rotate or is caused to stop one by one upon an interruption of the yarn flow. The only difference would be that if the machine is not designed for disengagement of individual spindles, then the apparatus of the invention must be equipped with some form of means for applying a braking force to the spindle. One such means is shown in the drawings and consists of a solenoid 170 (FIGS. 12, 33 and 34) mounted by means of a bracket on a horizontal frame member of the carriage C. At its supported end, solenoid 170 is displaced to one side of the axis of the position requiring attention and extends obliquely toward the spindle axis. The armature of the solenoid carries at its extreme inner end a grooved arcuate brake shoe 172 having a surface of suitable friction material, the configuration of the shoe being designed to engage the top flange of the spindle whorl and bring the same to a halt, the driving belt slipping on the whorl.

F. BOBBIN MAGAZINE

Locating the free end of yarn on the periphery of a wound package by a mechanical instrumentality is difficult under the best of circumstances. This is particularly true in the case of spun yarn as such yarn inevitably carries a certain amount of loose fibers on its surface which tend to become entangled with contiguous strands. If desired, the apparatus of this invention could be designed to recover the free end of yarn from the partially wound bobbin and manipulate that end for reunion with the free end from the spun roving. It is preferred, however, for the bobbin being wound to be doffed when the yard being wound breaks, irrespective of the extent it may be wound.

The invention thus serves to don an empty take-up bobbin on the spindle of the spinning position undergoing servicing, to which bobbin the free end of the spun roving can be fixed.

In order to furnish a supply of empty bobbins as well as a receptacle for receiving the doffed bobbins, the carriage C of the present apparatus includes a magazine section generally designated M which best appears in FIGS. 1 and 2. Magazine M is defined by a removable front or outside wall 180 (removed in FIG. 1), an inside wall 182 spaced from the outside wall a distance slightly in excess of the maximum diameter of a fully wound bobbin, and two end walls 184, 186 spaced apart longitudinally of the carriage a distance somewhat in excess of the length of the bobbin, say about twice such length as illustrated. Together, these walls form a high, rather thin compartment standing vertically on the deck 70 of carriage C with its upper end open. Arranged in the open end of the compartment and extending downwardly therein is a curved chute 188 in which a supply of empty bobbins B is arrayed one after another generally in a line. At the lower right-hand end of chute 188 is an empty bobbin magazine gate for receiving the leading bobbin in the chute and delivering the same to a ready position for donning on an empty spindle, this gate being generally designated 190.

As seen in FIGS. 1, 2 and 6, gate 190 consists of two walls 192 and 194 joined at right angles with a floor 196 at their lower end. At the top and bottom of the corner defined by the intersection of walls 192, 194 are pivot pins 198 journaled in inwardly directed ears 199 (FIG. 2) provided for this purpose on the adjacent sector of the rear compartment wall 182. Hence, the angular gate is adapted to rotate on a vertical axis about its corner and the exposed edge of the gate floor 196 is suitably curved to allow such rotation within the confines of the compartment. A V-shaped block 200 projects inwardly from the wall 194 in order to steady the upper end of the empty bobbin within the gate and a vertically spaced pair of deflector arms 202 (FIG. 2) project arcuately from the outside edge of the wall 182 through an angle of approximately 90 degrees.

The actuating mechanism for the gate is an air cylinder 204 arranged beneath the lower end of the chute, the free end of the air cylinder piston 206 being secured to one leg of a bracket 208. The other leg of the bracket is pivotally connected on the underside of the gate floor and the opposite end of cylinder 204 is pivoted on a cross piece 210 bridging the outside and inside compartment walls in order that the air cylinder may swing to follow the pivotal movement of the gate. To maintain further control over the descent of the empty bobbins into the gate, an air cylinder-operated bobbin stop 212 can be provided at the end of the chute just before the gate, the free end of the cylinder piston projecting into the interior of the chute to prevent further downward displacement of the leading empty bobbin except for a period immediately following return of the gate to bobbin receiving position as shown in solid lines in FIG. 2. At this time, compressed air is supplied to cylinder 214 to withdraw the stop 212 and allow the empty bobbin to enter the gate.

As can be seen in FIG. 6, the forward end of the deflector arms 202 can project slightly inwardly into the compartment at a sharper angle than the normal curvature thereof, as at 215, in order to insure deflection of the leading empty bobbin out of the path of the swinging gate. Obviously, if no empty bobbins are present in the chute 188, that chute must be reloaded before the apparatus will be capable of servicing further spinning positions on the frame. A sensing finger 216 extends into the interior of the gate from the wall 192 from a switch 218 mounted on that wall. The finger 216 is bent so as to be engaged by any bobbin present within the gate to actuate the switch 218 and give a control indication of the presence of an empty bobbin in position for donning on the

spindle being serviced. When chute 188 is empty, switch 218 causes the carriage to travel to one end of the frame to receive a fresh supply of empty bobbins.

When the magazine gate 190 is in its normal closed position, its end wall 194 together with the corresponding portion of the compartment end wall 186 and the intervening sections of the compartment front and rear walls define a vertically extending opening 220 communicating with the interior of the magazine compartment below the empty bobbin supply chute 188. For ease in subsequent handling, the doffed wound bobbins are preferably maintained in some reasonably orderly condition in the lower section of the compartment rather than in random disarray. This result can be achieved by interposing a curved chute 222 to receive the bobbins passing through passage 220, the chute at its upper end merging smoothly into the compartment side wall 186. Chute 222 terminates at its lower end a distance spaced from the opposite compartment side wall 184 sufficient to accommodate the length of the bobbins, extending from that point vertically downwardly to serve as a false wall 224 maintaining the wound bobbins P in substantial vertical alignment.

G. BOBBIN TRANSPORT MECHANISM

Means must, of course, be available for transporting the doffed wound bobbins and empty bobbins from and to the spindle at the position being serviced. For this purpose, in the illustrative embodiment, a supporting post 230 is rigidly mounted on carriage deck 70, passing through that deck to a point slightly below it and extending vertically upwardly from the deck to a point well above the plane of the roll stand rail 32. Post 230 has a central bore and receives for rotation therein, a shaft 232, see FIG. 2. As shown in FIG. 7, the shaft is driven from its lower end by means of a drive sprocket 234 keyed to that end and around which passes a drive chain 236. Chain 236 is provided with an outwardly projecting lug 238 at a convenient point thereon and lug 238 is engaged from opposite directions on the free end of a piston 240 of an air cylinder 242. To give a linear stretch on the path of drive chain 236 to accommodate the throw of the piston, an idler sprocket 244 is disposed in slightly spaced relationship to drive sprocket 234 for traversal by a chain 236 in a generally oblong path. The arc of rotation of shaft 232 can obviously be altered by adjusting the throw of piston 240, an arc of approximately 135 degrees being found satisfactory for the particular arrangement shown in the drawings. It will be seen that the mechanical drive just described is adapted to impart a positive, rapid rocking movement to the shaft 232 and that any other driving connection meeting these criteria could be substituted without substantially affecting the operation of the apparatus.

At its upper end (FIGS. 1 and 2), shaft 232 is keyed for rotation therewith to a bobbin transport arm 250 projecting generally radially from the shaft axis. The arm 250 at its end carries a bobbin elevator rod 252. It is important to the successful manipulation of the bobbins during doffing and donning that the elevator rod move along a rigidly fixed vertical path with minimum deflection and such support can be obtained for rod 252 by a plurality of guide blocks 254 through which the rod is adapted to slide. The block 254 is mounted in vertically spaced relationship on the transport arm which, as is apparent from the drawings, is of massive construction to provide a firm stable footing for the guide blocks. Transport arm 250 also carries a compressed air cylinder 256 for operating the elevator rod, the cylinder being directed upwardly from its position supported on the outer end of transport arm 250 in generally parallel spaced relationship to elevator rod 252, the piston rod 258 of the cylinder being connected at its far end to the extreme upper end of the operating rod as at 260. Operating cylinder 256 is preferably of the double-acting type so as to provide positive, controlled reciprocation of rod 252 between determined upper and lower limits.

At its lower end, elevator rod 252 carries a cam-operated 3-jaw clamp generally designated 262. This clamp consists of three levers 264 having a V-shaped jaw 266 at one end which are fulcrumed in a 3-legged bracket 268 fixed on the extreme lower end of rod 252. The opposite ends of the levers 264 are inclined for engagement with the periphery of a conical actuating cam 270 slidably encircling rod 252 and which is coupled to the lower face of a pneumatically expandable bellows 272. The bellows is of torroidal configuration so that the elevator rod can pass through the central opening thereof, its upper end being held against movement relative to the rod by means of a sleeve 273 fixed on the rod. When compressed air is admitted to bellows 272, the actuating cam 270 is urged downwardly along the rod, rocking levers 264 about the arms of bracket 268 to bring the jaws 266 to gripping position.

The axes of magazine opening 220 and the spindle 46 are preferably equidistant from the pivotal axis of bobbin transport arm 250, lying on the same circular path followed by the elevator rod 252, the spindle axis being situated at one end of such path and constituting the normal, inoperative position for the rod, while the opening is at the other end of such path. The three functions formed by the mechanism, namely, of positioning the transport arm, reciprocating the elevator rod and actuating the bobbin clamp are controlled by separate pneumatic means and can, therefore, be carried out essentially independently of each other, although the sequence is, of course, fixed. Consequently, the timing of these operations can be precisely controlled in coordination with the other operations to be carried out by the apparatus, of course, fixed.

Consequently, the timing of these operations can be precisely controlled in coordination with the other operations to be carried out by the apparatus.

I. ROVING CUT-OFF

Under certain circumstances, it is desirable that the flow of the roving into the stand of drafting rolls 36, 37, 38 be ended and the apparatus of the present invention preferably, although not necessarily, includes a roving cut-off device which can be actuated to sever the roving upstream of the drafting rolls. As the bobbin transport arm 250 has a normally inoperative position situated generally above and outwardly of the roll stand, except when actually engaged in transferring bobbins between the spindle and the magazine, this arm forms a particularly convenient medium for supporting such a cut-off device. As appears in FIGS. 1 and 2, a pneumatic cylinder 274 can be anchored at one end of a bracket 276 on a face 278 of the arm 250 lying to one side and somewhat behind the elevator arm assembly, the cylinder 274 extending angularly downwardly toward the ingress end of the roll stand. A piston 280 working in cylinder 274 carries at its extreme end a knife blade 282 which is projected when the cylinder is supplied with air to a position engaging with the roving entering the draft roll stand. More reliable cutting action can be obtained if the knife blade enters a small clearance provided between two closely spaced parallel guide rolls (not shown) arranged for this purpose in the path of the knife edge and passed over by the roving. Once separated, the leading end of the roving merely dangles downwardly from its supply bobbin until rethreaded into the draft rolls by the machine attendant.

J. STRAND DELIVERY MECHANISM

It will be recalled that in the event the strand being spun at a given position breaks in the region downstream of the delivery pair of draft rollers, the free end of the drafted roving is swept into the aperture 66 of the "Pneumafil" suction system and is drawn away as fast as delivered by the draft rolls until the strand is rethreaded into the ring rail traveller and onto the take-up bobbin. As delivered by the drafting rolls, the attenuated but un-

twisted roving is extremely flimsy, lacking any appreciable tensile strength until twist is inserted therein. A feature of the present invention is means by which the drafted but untwisted roving is engaged or snared at the nip of the delivery pair of draft rollers 38, removed from the influence of the "Pneumafil" system, and conveyed into proximity with the spindle for threading thereon, all without disturbing the delicate coherence of the strand.

In general, the above result is accomplished in the present invention by a vortex suction nozzle (vortex nozzle I) which is elevated until its suction orifice is in close proximity to the nip of the delivery pair of draft rolls to attract the strand into the suction orifice, the vertical flow of air taking place therein imparting to the strand a twist such that the strand will have its tensile strength enhanced to a point permitting it to be manipulated with a reasonable degree of freedom, and thereafter gradually lowering the vortex nozzle along a predetermined path stretching downwardly to the region of the take-up bobbin and the ring rail, twist being imparted to the strand all the while to produce yarn. Advantageously, the yarn is twisted by the vortex nozzle I in the same direction in which the yarn is twisted in normal operation of the machine. One form of mechanism found satisfactory for accomplishing this result in practice will now be described with reference to FIGS. 8-10, in particular.

The nozzle (FIGS. 8 and 9) generally designated 288 has at its suction or ingress end a hollow tubular section 290 having at both ends portions of reduced diameter as at 292 and 294. The shoulder between the outer end portion 292 and the center portion is slightly beveled as at 296 and at equidistant points around the annular surface defined by the beveled shoulder are drilled a plurality of inwardly and rearwardly projecting apertures 298 intersecting tangentially with the internal surface of the bore 300. The end face 302 of the end portion 292 is likewise beveled. The opposite end portion 294 is press-fitted into the mouth 304 of an enlarged tubular discharge section 306 of the nozzle which is of substantially greater diameter than the ingress section 290 so as to accommodate an outwardly flaring discharge opening 308. The portion of the discharge section 306 adjacent the ingress section 290 is reduced in diameter and threaded as at 310 for engagement with one end of a nozzle cap 312 (FIG. 10). The internal diameter of cap 312 is greater than the external diameter of the ingress nozzle section except for a shoulder 314 formed at its unthreaded end for tight seating engagement with the flared end face 302 of the ingress section. An annular clearance 316 exists between the outer and inner peripheral surfaces of the ingress nozzle section and nozzle cap, respectively, to define an annular manifold for the jet apertures 298 into which manifold compressed air can be admitted through a suitable fitting 318 communicating with the interior of the cap. As the air under pressure flows through the jet apertures from the manifold, a rotating or spinning condition is created within the bore of the ingress nozzle section and a zone of negative pressure is set up in the bore 300 upstream of the convergence of the air jets.

To effect delivery of the strand, the vortex suction nozzle 288 is moved along a fixed path (FIG. 2) extending vertically forwardly of the spindle rail 44 and ring rail 52 and then arcuately over and beyond the spindle tip to a point proximate to the nip of the delivery draft rolls by means of a flexible chain 320 which is adapted to flex to follow the desired curved path. The chain 320 moves within a generally C-shaped enclosed track or housing 322 having an inner guiding portion 324 (see FIGS. 2, 11 and 12) extending generally upwardly from a point adjacent the platform 70 to approximately the level of the draft roll rail 32 in a configuration conforming to the path of the nozzle just described, and a storage portion 326 joined to the lower end of portion 324 through a 180° bend and stretching vertically upwardly from deck 70 to receive the major portion of the length of the chain when the nozzle is in inoperative position, as shown by solid lines in FIG. 2. Arranged within the curved section between the two por-

tions of the housing is a sprocket 327 in driving engagement with the links of the chain, the sprocket being driven by a variable speed electrical motor 328 (see FIG. 1) to permit adjustment in the rate of travel of the suction nozzle. The suction nozzle does not enter the housing along with chain 320 but follows along one side of the housing which is slotted throughout its full length for that purpose (see FIGS. 11 and 12). A rigid connection is maintained between the upper end of the chain 320 through a slide block 325 fastened to the upper link of the chain and including an exterior extension finger 329 (FIGS. 11 and 12) projecting through the housing slot, with a supporting rod 330 secured to the finger and to the nozzle cap 312. If desired, in lieu of the fitting 318 (FIG. 10), the supporting rod 330 can be tubular and serve as the air supply tube for the vortex nozzle, compressed air being admitted to the lower end thereof.

In order to give, for control purposes, an indication of the arrival of the vortex suction nozzle I 288 at the limits of its path of travel, a limit switch 336 is mounted on the storage section 326 of the chain housing adjacent the upper end, and a similar limit switch 338 is mounted adjacent the lower end of that section. The armatures of these switches project into the path of a detent (not shown) extending outwardly from the last link of the chain through the slot in the chain housing. The positions of limit switches 336 and 338 are so selected that the switch armatures are actuated by the detent just mentioned when the chain and suction nozzle have been fully withdrawn in the case of switch 336, on the one hand, and fully extended to the roving engaging position in the case of switch 338, on the other hand.

K. THREAD GUIDE REMOVING MECHANISM

In the specific embodiment disclosed in FIG. 2, the thread guide 40 as well as the articulated bracket section 42 of the thread board, lie when in normal operative position in the path of the bobbin elevator arm 252 and are removed from this position in order to permit passage of the three-jaw bobbin clamp to and from the spindle being serviced. When it is necessary to rock the articulated section of the thread board to an out of the way position, the particular mechanical arrangement employed is immaterial.

One simple design has been shown in the drawings, especially FIGS. 13 and 14, according to which each of the movable thread board sections is provided with a vertically extending (dotted in FIG. 13) rock finger 340 adjacent one of its side edges so as to be displaced from the axis of the guide as far to one side as possible. Cooperating with the rock finger 340 is the hooked end 342 of a piston rod 344 reciprocated by an air cylinder 346. When the rod 344 is projected forwardly, the hooked end 342 abuts rock finger 340 and, as its forward movement continues, rocks that finger and the corresponding thread board section through an arc of approximately 90° to the dotted line position of FIG. 2. The rod remains in extended position throughout the doffing and donning phase of the cycle of operation of the apparatus, the length of the hook 342 allowing the piston rod 344 to be offset from the spindle axis a sufficient distance to avoid obstructing the movement of the bobbin clamp. When the air pressure is cut off from cylinder 346, the rod 344 returns to a normal retracted position and in returning, engages the now upwardly extending thread board section 42 which swings downwardly to its normal operative position to allow the hook to pass.

L. SUCTION NOZZLE OSCILLATING MECHANISM

The present invention includes means for scanning the length of the forward draft rolls with nozzle 288 so as to attract the drafted roving at whatever point along such length it emerged, the nozzle having imparted thereto a limited oscillating movement to swing it along the nip of the rolls.

The mechanism for carrying out this function is sup-

ported on a horizontal platform 350 situated at a level approximating that of the roll stand and suitably fastened to a portion of the carriage C adjacent the top of the inner guide post 112 of the sub-carriage I. Resting on the surface of the platform 350 is an elongated slide 352 (see FIGS. 13 and 15) which is guided along a linear path by means of a suitable connection with the platform 350, such as a slot and cooperating pins. Adjacent the end of the slide nearest the draft rolls is an upstanding boss 354 on which is fastened for pivotal movement about the axis of the boss a nozzle swing arm 356. The end of swing arm 356 facing the draft rolls is formed with a longitudinally extending central recess 358 opening into a flaring mouth 360. Provided on the top of the suction vortex nozzle adjacent its discharge end is a pin 362 (shown in dotted lines in FIG. 13) that is adapted to be engaged within the recess 358 of the swing arm 356 when the slide 352 is fully extended on platform 350, the flaring mouth 360 insuring that the pin enters the recess irrespective of the precise location of the suction nozzle within the limits of the length of the draft rolls.

The opposite end of the swing arm is connected to a vertically arranged electric motor 364 to receive a limited oscillating motion from that motor. Thus, the motor shaft 25 can carry a disc 361 having an eccentrically located stud 363 thereon engaged for sliding movement within an elongated longitudinal slot 365 in the arm end. The arm end can, of course, be vertically offset if necessary to accommodate the electric motor. Controlled movement of the slide 352 on its track is effected by an air cylinder 366 having the free end of its piston rod 368 fastened to the rear of the slide. Admission of air to cylinder 366 thrusts the slide forward toward the vortex suction nozzle 288 already in operative position at the nip of the delivery rolls, the limit of travel of the slide being so determined that the pin 362 on the nozzle will seat comfortably in recess 358 when the slide is fully extended. The forward end of the swing arm 356 may be tilted upwardly, as at 356', for better conformity with the inclination of the suction nozzle if desired. With the pin seated in recess 358, the motor 364 can be actuated to oscillate the remote end of the arm which transmits such motion to the pin and, thus, the nozzle itself. A limit switch 367 can be fastened on platform 350 for engagement by a stop 369 moving with slide 352 to automatically energize motor 364 when the slide is fully projected and to cut the motor off when the slide returns to normal position. The throw of the eccentric disc driven by the motor 364 is selected so as to swing the nozzle through an arc corresponding approximately to the axial dimension of the draft rolls. Prolonged energization of motor 364 is not necessary as only several revolutions will suffice for the nozzle 288 to accomplish its purpose.

M. YARN SENSING MECHANISM

Reference has already been made to the existence on the apparatus of this invention of a yarn sensing device for detecting the presence or absence of yarn at the several spinning positions as the carriage traverses the length of the frame. In the illustrative embodiment, this sensing device is associated with the platform 350 supporting the nozzle scanning mechanism just described; the sensing device can, therefore, be most conveniently described at this point. As shown in FIGS. 13 and 16, depending from the underside of the platform 350 is another slide 370 having a downwardly extending leg 372, this slide likewise being guided for movement along the linear path by means of a suitable connection, such as a slot and pins, with the platform. On the side of the leg 372 facing the frame are a spaced apart pair of lugs 374 adapted to pivotally support a yarn sensing wire 376. As the wire 376 must sense the yarn in both directions of travel of the carriage, it is preferably formed as a loop symmetrically shaped with respect to a vertical plane passed through the axis of the spinning position transversely of the length of the frame,

the ends of the loop being bent to serve as the pivots journaled in the lugs 374.

A switch 380 is mounted on the under side of the slide 370 generally above the pivoted end of the feeler wire, the armature 381 of the switch projecting downwardly and terminating in a hook in which one leg of the loop lightly rests. Preferably, wire 376 is formed of relatively stiff but lightweight material so as to have a minimum of inertia, although the weight of the wire must obviously be sufficient to actuate the switch. So long as yarn is present at the particular position being passed by the apparatus at a given time, the feeler wire will be held upwardly by the yarn, relieving the switch armature of its weight. If yarn should be absent, however, the wire swings downwardly against the hook of the armature closing the switch. The feeler wire will, in any event, swing downwardly between spinning positions. This does not, however, result in a false indication being fed to the apparatus as the circuit which includes the sensing switch is energized only when the carriage is in registration with each spindle position. For example, the spindle position registration switch can be connected in series with the yarn sensing switch so that the circuit is closed only when both of these switches are in proper relationship, as will become clearer from the subsequent explanation of the circuit diagram.

It will be recalled that in the embodiment illustrated, the doffing and donning mechanism requires an unobstructed path above the spinning position being serviced during the doffing and donning stage of the apparatus cycle. The slide 370 is, accordingly, adapted to be retracted to remove the sensing wire from the path of the bobbin elevator arm by means of an air cylinder 382 having its piston 384 attached at its free end to the slide leg 372. After the rethreading operation has been completed, air is exhausted from cylinder 382, allowing rod 384 to return to normally extended position with the feeler wire situated for sensing the yarn at the next position. As indicated in FIG. 13, the thread removal mechanism can also be suspended from platform 350, hanging from a bracket beneath cylinder 382.

N. STRAND THREADING MECHANISM

(1) *Ring traveller threading.*—The operation of the delivery mechanism will, it will be recalled, result in the yarn, with the twist therein imparted by the suction nozzle vortex, assuming a path of dog leg shape extending from the nip of the delivery draft rolls, forwardly and downwardly to a point below the ring rail 52, as determined by the rest or inoperative position of vortex nozzle I 288. As is apparent, the rate of descent of the suction nozzle cannot exceed the delivery rate of the draft rolls if the strand is to remain intact and preferably the sprocket 327 driving the chain is driven at a rate slightly less than the delivery rate of the draft rolls. Such excess length of the strand as may be created because of this differential is taken up by the suction effect of the nozzle, projecting out of the nozzle discharge opening in the form of a tail. Unless this tail is allowed to grow to extreme proportions, it causes no difficulty in the operation of the machine. With the strand in this position, it is preferably threaded into the traveller of the spinning ring and ultimately attached to the bobbin itself, and the mechanism for accomplishing these threading functions will now be described.

As those spinning positions not being serviced by the apparatus of the invention must continue to operate, it follows that the ring rail of the frame continues its traversing motion without interruption and the instrumentalities utilized in the strand threading steps must be adapted to accommodate the ring rail motion. This is made possible by mounting all of the threading instrumentalities on the vertically movable subcarriage I, already described, which by virtue of the engagement of the opposed guide rollers 128, 130 with the rail 126 projecting from ring rail 52 moves bodily with the ring rail so that the relative position

of all parts mounted thereon remains constant with respect to the ring rail.

Referring now to FIGS. 17-20, showing the threading steps in detail, the first step is to deflect the strand, from the path taken in the descent of vortex nozzle I 288, to a position extending around a portion of the exterior periphery of ring 50, permitting engagement of the ring traveller 54 therewith. To this end, there is slideably mounted on a shelf 390 (FIG. 2) supported in vertically spaced parallel relationship to the platform 110 of the sub-carriage I an elongated threading fork 392. This fork is formed with the longitudinal slot 394 extending through most of its length and terminating in a transverse extension 396 at its remote end. A pair of spaced apart guide studs 398 are passed through this slot with their ends secured to the shelf 390 to allow free sliding movement of the fork thereon along the path determined by the studs 398 and slot 394. The studs are so arranged that a line passed through their midpoint extends substantially tangentially to the outer peripheral surface of ring 50. The end of the fork near to the ring rail is offset downwardly as at 399 and is formed with a deep notch as at 400 to engage and hold the yarn therein.

Movement of threading fork 392 inwardly will bring the notched end into engagement with the strand, as shown in FIG. 18, and then deflect the yarn across the top surface of the ring rail along a path generally tangent to the rail periphery as shown FIG. 19. Just before the fork is fully extended inwardly, the curved slot end portion 396 comes into engagement with the outermost of the studs 398, imparting to the notched end of the fork an abrupt swinging movement leftward, as shown in FIG. 20, toward the spindle post 46. The combined effect of this lateral and axial motion is to wrap the strand from the point of tangency with the ring periphery around a short arc of that periphery, rising over the rim of the ring flange to the crotch of the notch 400 and then generally upwardly toward the draft rolls (see FIG. 20). At the extreme inward position of the threading fork, a stop 402 thereon contacts the armature of a switch 404 which closes to give a control indication that the fork has completed its movement.

The driving force for the threading fork 392 is supplied by an air cylinder 406 having its rear end held in abutting relation to a brace 408 on shelf 390, the piston rod 410 of the cylinder having its free end affixed to a push block 412 rigidly joined to the outer end of the threading fork through a link 414.

During the just described action, the traveller 54 rests at some point around the flange of ring 50. It has been discovered that with the thread in the deflected position just described and shown in FIG. 20, if the traveller is propelled around the ring, it will ride up on the strand to become engaged therewith. The impetus for so moving the traveller can be conveniently derived from an air jet provided by jet tube 420 extending from a nozzle 422 supported on a lateral extension 424 of threading fork 392, the jet tube being of such length and curvature as to direct the jet at an acute angle against the inner peripheral wall of the ring. Sufficient air from this jet follows around internal ring surface as to act on the extremely light weight traveller 54 and propel it to a position so as to engage with the strand irrespective of the initial location of the traveller around the ring.

(2) *Bobbin threading.*—During the spinning operation, the spun yarn passes from the traveller 54 to the periphery of the bobbin B arranged at the center of the ring 50 and means are provided for moving the strand from the position in which it is held by the traveller threading mechanism just described to the interior of the ring and ultimately into engagement with the bobbin or spindle. Along the inside edge of platform 110 to one side of the path of the threading fork 392 is a vertically extending load-bearing panel 430 best seen in FIGS. 17 and 21-23, the leftward end of this panel as seen in these

figures terminating to the right of the axis of the spindle position. Hung on this panel adjacent the left end from a stub shaft 432 is a rockable arm 434 from the lower end of which extends a strand lift fork 436 terminating at its remote end in a deep inwardly extending notch or fork 438. In the inoperative position shown in FIG. 17, rock arm 434 extends obliquely downwardly to the right while the lift fork depends generally downwardly and to the left from the end of the arm towards the strand which extends below the ring rail at a slight angle relative to the spindle axis.

The purpose of the forked end 438 is to engage the strand as the lift fork and rock arm pivot around shaft 432 and such engagement can be made somewhat less critical by bending the outer tine of the forked end out of the vertical plane towards the spindle axis as at 440, to increase the transverse distance between the two points of the fork between which the strand must pass. The force for rocking these parts is supplied from an air cylinder 442 having its piston rod 444 connected to rock arm 434 by a link 446. The remote end of link 446 is bent inwardly and engaged in an elongated slot 448 cut in rock arm 434 in order that link 446 may move in a linear path while the rock arm pivots. The operative position of the forked end 438 of the lifter fork 436 is relatively critical and to permit fine adjustment to be made, the connecting link 446 is preferably adjustable in length by means of at least one threaded sleeve 450 joining link sections. As the lift fork reaches fully projected position, a lifter fork limit switch 452 is actuated by a protuberance 454 provided for that purpose on rock arm 434 to give a control signal.

With the strand in the position assumed to exist at the start of this portion of the description, air cylinder 442 is actuated, the movement of its rod 444 being transmitted to the rock arm 434 and thence to the lift fork 436, these two parts pivoting about the axis 432 to bring the forked end 438 into engagement with the strand. Continued movement causes the forked end to slide up the length of the yarn stretching below the top of the ring by shifting the same leftwardly from the displaced position it occupies under the influence of threading fork 392 and finally upwardly above the plane of the ring rail flange. There being no downwardly-acting restraining force on the yarn other than the traveller, the strand when elevated above the ring slides over the top of the ring, assuming generally the position shown in FIG. 23. In this position, the strand extends chordally across the ring just to the side of the spindle, one end of the chordal section being engaged in the traveller and the other in the crotch of the lift fork.

A considerable tail of yarn extends downwardly from the crotch of the lift fork to suction vortex nozzle I 288 and the possibility of operating difficulty arising from entanglement of this end in some part of the mechanism is considerably reduced by disposing of the tail as soon as the strand has assumed the chordal position just described. The tail can be cut off by movable shear blade 460 pinned to the lift fork 436 as at 462 for independent pivotal movement towards and away from a fixed shear blade 464, juxtaposed with the unbent tine of the fork 438. Constructed integrally with the movable shear blade 460 is an operating handle therefor 466 of generally U-shaped configuration, the end of the U opposite to blade 460 being rounded as at 468 and of such a length that continued elevation of the lift fork brings the rounded handle end into abutment with the undersurface of fork 392 closing the movable shear blade 460 against the fixed blade 464 to sever the strand therebetween. The movable blade is normally held in open position by means of a tension spring 469 hooked at one end onto a pin projecting outwardly from the base of the operating handle and at the other on a similar pin on the lift arm 436 adjacent its junction with rock arm 434.

Actuation of the movable shear blade 460 produces a free strand end remaining instantaneously in the posi-

tion stretching chordally across the top of the ring, and the final step in the threading operation is to engage the free end thus produced and attach it to the base of the bobbin for subsequent winding thereon. For this purpose, 5 a vertically directed air cylinder 470 (see FIG. 32) is arranged adjacent the supporting post 230 for the bobbin transport arm 250 with the piston rod 472 of the cylinder terminating in a bracket 474. The undersurface of the bracket is pinned as at 476 to a slotted track 478 stretching vertically in parallel relationship to the axis of the air cylinder and attached to post 230. Anchored on the horizontal leg of the bracket 474 is the outer end of another air cylinder 480 extending horizontally generally towards the axis of the spindle position being serviced. Secured in a cradle 482 held on the end of the piston rod 484 is a second suction vortex nozzle 486 (vortex nozzle II). Except for a curved suction tube 488, extending from the suction orifice of the nozzle, details of the nozzle construction are the same as those described in connection with vortex suction nozzle I 288 and will not be repeated here.

From what has been said, it will be apparent that the air cylinder 480 functions to position suction tube 488 within the confines of ring 50 generally beneath the chordally extending section of the strand thereon, while the cylinder 470 elevates suction nozzle II 486 to proper vertical position underneath the ring rail 52. As has been explained, the reciprocating motion of the ring rail is continuous, whereas the cylinder 470 is mounted on the vertically fixed carriage deck 70. The relative movement of the two can be coordinated in any suitable fashion. If desired, admission of air to cylinder 470 can be controlled in timed relation to the reciprocating motion of the ring rail. Such elaborate measures are not required, however, provided the air cylinder 480 is actuated in advance of cylinder 470 so that the vortex nozzle II 486 is projected to its inward operative position while still positioned bodily below the lower limit of reciprocation of the ring rail, cylinder 470 thereafter being actuated to elevate the suction nozzle against the ring rail. Proper spacing can be maintained between the ring and the body of the nozzle by selection of suitable vertical dimensions of the cradles 482 and of a resilient button 490 preferably fixed on the top face of the cradle to lessen the shock of abutment between the nozzle and ring rail. The nozzle 486 must follow the motion of the ring rail while in contact therewith and the pressure of the air admitted to cylinder 470 is so regulated as to permit the piston the necessary movement.

It has been discovered that if the suction tube 488 extending upwardly from vortex nozzle II 486 is positioned in reasonably careful relationship to the chordally extending thread and the nozzle is in operation at least by the time the thread is sheared, re-engagement with the 55 sheared end of the yarn can be established quite effectively without loss in continuity with the strand. The thread end is attracted almost instantaneously into the suction tube and thence into the vortex nozzle itself where the vortical forces reinsert therein whatever degree of the 60 twist that may have been lost in the course of the transfer of the strand from one nozzle to the other. With the severed end securely lodged in the vortex nozzle II 486, the strand can be drawn downwardly through the ring opening alongside the spindle and with the strand in this position 65 a bobbin B is placed on the spindle. With the bobbin in this position, attachment to the bobbin can be achieved in a very simple manner. For this purpose, a notch 494 (shown in dotted lines in FIG. 23) is provided on the periphery of the bobbin adjacent its base. The strand is held against that periphery by the suction tube and rotation of the bobbin causes the notch to catch the strand and wind the same thereon, the end of the strand backwinding on the bobbin and pulling free of vortex nozzle II 486 under the superior force developed by the rotation of the bobbin. Once rotation of the bobbin has been

initiated, vortex nozzle II is retracted and lowered to its normal out-of-the-way position.

O. FULL BOBBIN CUT-OFF MECHANISM

A preferred feature of the present invention is a device for cutting off the flow of yarn to a given bobbin when that bobbin has been fully wound to a desired degree. The bobbin so freed to its supply of yarn can then continue to rotate with the yarn that would be otherwise running thereto being aspirated into the system until the position in question can be serviced by the present apparatus. A preferred embodiment of a simple mechanical cut-off device has been designed for incorporation into the present apparatus and will now be described with references to FIGS. 2 and 24.

This device is associated with the ring rail 52 and takes the form of a generally C-shaped lever 500 fulcrumed at its lower leg on a pivot axis 502, the lower leg being extended longitudinally to form a shoe 504 for contacting the periphery of the wound bobbin in an out-of-the-way position below the ring rail. The upper leg of the C-shaped lever is extended upwardly, as at 508, above the ring rail and terminates in a forwardly or laterally projecting nose 510 which is adapted to cause the spun yarn to break when projected into the path of the yarn running to the ring rail. The curvature of shoe 504 is such that engagement with the peripheral surface of a fully wound bobbin rocks the lever arm 500 to a position interposing nose 510 in such yarn path.

Remembering the particular configuration of bobbin that is utilized with the spinning frame for purposes of this invention, it will be seen that the enlarged base of the bobbin would cause the present yarn cut-off device to experience premature actuation if the shoe 504 were to come into contact with the enlarged base while the ring rail was at the lowermost point of its path. To avoid such an undesirable occurrence, a plurality of the cut-off levers 500, including all of the levers on a given side of the frame, if desired, are arranged with their pivot axes 502 on a common shaft, displacement of the levers axially along the shaft from a position in general alignment with the spindle position being prevented by means of a stop collar 512. The shaft serving as a collective pivot axis 502 is supported for swinging movement towards and away from ring rail 52 by a swing arm 514 depending from one end of a bracket 516 having its other end fixed to the rear edge of the ring rail, as at 517. A lateral extension 518 projects inwardly therefrom to terminate in a toe 520, a cam surface on a plate 522 (FIG. 2) located at a vertical position corresponding to a point adjacent the upper limit of travel of the ring rail. It will be appreciated, of course, that the cam surface 522 need not be duplicated at every position of the frame but only at sufficient points along the frame length as to impart a positive inwardly swinging motion to the common pivot shaft 502 when the ring rail approaches its upper limit of travel. With the pivot shaft held in its position near the ring rail, the shoe 504 will at any spinning position where the bobbin has achieved the desired maximum size, be contacted by the bobbin periphery, causing the nose 510 to be projected inwardly to stop the flow of yarn thereto. Conversely, at those positions where the bobbins are only partially wound, the cut-off lever will remain in inoperative position and spinning will continue without interruption. As the ring rail leaves its uppermost position, the common pivot shaft is free to swing outwardly under its own weight, or under the impetus of some positive bias if desired, preventing actuation of any of the cut-off levers until the ring rail next approaches its upper limit.

Alternative embodiments

A. MODIFIED POWER SUPPLY

The arrangement for the main embodiment that has been described for this point is peculiarly well suited for use in older mills which are not equipped with facilities

for the production and storage of compressed air in large amounts and, in particular, the delivery of compressed air to a plurality of points in the spinning room of the mill. In such mills, the equipment is already present for generating and/or supplying electrical current and extension of lines to deliver such current at whatever point of the mill poses no significant problem. For more modern mills, one could employ an alternative embodiment which permits certain saving in cost as well as some simplification.

This alternative embodiment is illustrated in FIGS. 26 and 27 and, in general, involves the elimination of the so-called "third rail" electrical supply arrangement of the previous embodiment together with the compressed air generating means in favor of an "umbilical cord" extending from supply conduits situated at the frame directly to the carriage. In FIG. 26, only those parts differing from the main embodiment will be described and it will be understood that the remainder of the machine will be as in the previous embodiment. In these drawings, the numeral 530 is applied to one or more conduits rising from the floor beneath the spinning frame through the bottom of a U-shaped channel 541, there being preferably two of such conduits 530, one connected to a source of compressed air and the other housing an electrical line with a suitable terminal connection. To each of these conduits is connected one end of a supply line 534 having its other end connected to a receptacle 536 mounted on the carriage C of the invention for movement therewith. Receptacle 536 distributes the particular medium supplied by the lines in whatever fashion for which provision has been made.

The lines 534 must, of course, be sufficiently long to permit the carriage to travel the full length of the spinning frame and some means are desirably furnished to accommodate the length thereof in orderly manner during the travel of the carriage. One arrangement for achieving this result is shown in the drawing in the form of a rolling pulley block 540 for taking up the excess of the lines 534, such as hose and cable, such block being disposed within the U-shaped channel 541 beneath the spindle rail in a more or less unobtrusive position. Block 540 carries a large pulley 542 around which the lines extend approximately 180°, this pulley rolling on the bottom surface of channel 541. A small pulley 544 is mounted on the block in spaced parallel relationship to large pulley 542 and is approximately half way encircled by a drive cable 546. This cable is connected at one end to a tension maintaining spring 548 located adjacent one end of the frame (assuming that the supply conduits 530 are situated, as preferred, approximately midway of the frame). After wrapping around the small pulley 544, the drive cable 546 passes around pulleys 550 and 552 provided at opposite ends of the frame to connect finally with an eye bolt 554 affixed to the carriage C.

The operation of the excess line and cable take-up device will be obvious, the take-up pulley block following the direction of movement of the carriage to pay out or take up hose as necessary.

B. MODIFIED YARN SENSING MECHANISM

As indicated previously, the present apparatus is not dependent upon the use of the particular yarn sensing array used in the illustrative embodiment for detecting the initial presence or absence of the yarn in its normal operating position at the successive spinning positions of the frame. A somewhat different form of detecting device that could be substituted with equally good results will now be described.

In accordance with the modified yarn sensing device as illustrated in FIGS. 28 and 29, the articulated front section 42 of the thread board has attached thereto a generally downwardly directed bracket 560 on the ends of which is pivoted a yoke 562. The self-threading guide eye 40' has a rear leg 563 rigidly affixed to yoke 562 at

approximately its midpoint. One leg 564 of the self-threading guide eye is extended forwardly of the front section 42 to terminate in a downwardly bent end on which is welded a small baffle plate 566. The strand Y (FIG. 29) passing through the eye 40' maintains the baffle 566 elevated. When the strand no longer runs through the eye (FIG. 28), the baffle drops and is held in lowered position by the rear leg 563 engaging the bracket 560.

Mounted on the inside of carriage C adjacent to the draft roll rail and in an appropriate longitudinal position for cooperation with the baffle plate 566 is an air jet switch array generally designated 568. This array consists of an elongated tubular housing 570 which is adapted to be projected towards and retracted from the draft rolls as necessary to effect the sensing of the yarn and to clear the path for the doffing and donning of the bobbin. Housing 570 is notched as at 572 in its upper surface adjacent the extreme inward end, such notch being defined on its inside by wall 574 forming one wall of a compressed air compartment 576 to which compressed air is fed via an air tube 578. At approximately the center of wall 574 is a jet nozzle 580 pointed longitudinally of the housing towards the opposite side of notch 572. On such opposite side, housing 570 is open and in this opening is a target plate 580. Target plate 580 is mounted on the armature 581 of a switch 582 and it will be seen that when the baffle plate 566 carried by the self-threading guide eye is maintained in an elevated position out of the notch 572 by virtue of the engagement of the running yarn with the guide eye, the jet nozzle 580 is effective to direct a blast of air from the compressed air compartment against the target plate 580 to bias that plate and the switch armature to one extreme position. When, on the other hand, the yarn is absent at the particular guide eye, the eye and the baffle plate pivot in a counterclockwise direction, lowering the plate into notch 572. In this position, the force of the jet nozzle is obstructed and the target plate and switch armature are free to move under a normal bias to the other extreme position, this change in position of the switch armature serving to give a control indication of the absence of the yarn.

CONTROL AND TIMING DIAGRAMS

FIG. 30 is a complete diagram of the control circuitry employed in regulating the actuation and operation of the mechanical and pneumatic components heretofore referred to in connection with the mechanical description of the illustrative working embodiment of the invention.

An explanation of this diagram will now be given.

L_1 and L_2 designate the sides of power supply, preferably carrying low voltage, from which the circuit of the invention draws electrical current, these sides being connected into the circuit through master switches 600, 602 so that the entire circuit can be quickly de-energized if necessary. Each of the sides is also fused as at 604 and 606 for further protection. For ease of illustration, the return lines for virtually all of the ultimate operative components of this circuitry are not shown but are indicated merely by an arrow together with a caption indicating that such lines extend to the particular side of the source specified. This being understood, 608 represents a terminal to which all of the return lines for side L_2 are connected and 610 represents a similar terminal for side L_1 . Connected to the fuse 606 for side L_1 is a line 612 which connects at its other end to a switch 380 that is actuated, it will be recalled, by the yarn sensing feeler wire 376. This switch is of the normally closed type and is maintained open by the tension in the yarn when yarn is present at a position, closing when such yarn is absent. In its normally closed position, it connects with a line 614 extending to one side of a switch 132. The latter is the spindle position registration switch which is normally closed but is maintained in open position by engagement with the notches 130 provided on the top flange of the

guide rail moving with the spindle rail. When closed, switch 132 connects line 614 with a line 616 extending to one side of one armature of a double armature relay 618, which armature is designated 618' and the other armature 618''. Relay 618 has a built-in time delay at actuation and when de-energized, its two armatures are open. The holding coil 618c of the relay is connected at one end to a line 620 which is in series with the switch 218 which, when closed, connects line 620 to the side L_1 . Switch 218 is the empty bobbin sensing switch provided on the swing gate of the bobbin magazine so as to close when an empty bobbin is in position for delivery to the bobbin doffing and donning mechanism. When, however, no bobbin is in such position, switch 218 opens, releasing the relay armatures and thus breaking the connection between line 616 and the remainder of the circuit. As the magazine is reloaded, the arrival of the first empty bobbin at the gate closes switch 218 but as sufficient time must be allowed for the magazine to be completely loaded, the closing of the relay, even though its coil 618c is energized, is correspondingly delayed.

The other side of armature 618' connects with line 622 that extends to one side of a switch 624, referred to herein as the carriage restart switch, the purpose of which will be explained further along in this description. This switch is normally closed and is moved mechanically to open position by means of a control cam 626 affixed to a main control shaft 628 provided on the apparatus. When closed, the switch 624 connects into the circuit a line 630 that extends to one side of a holding coil 632c of a triple armature relay 632, the other side of the coil being connected to line L_2 . Relay 632 includes the three armatures 632', 632'' and 632''' and is referred to herein as the carriage drive relay, its basic purpose being to control the propulsion of the carriage. Armature 632' is open when the relay is de-energized, closing when the relay is actuated to make connection on one side with a line 634 which joins with line 622 prior to the latter's connection with switch 624. The other side of the armature 632' is connected by line 636 to a line 638 which extends to main line 611 originating from side L_1 of the power source. Since lines 638 and 636 thus carry current continuously from main line 611, closure of armature 632' sets up a holding circuit through lines 634 and 622, switch 624, and line 630, for the relay coil 632, holding relay 632 in energized position irrespective of the subsequent condition of switches 380 and 132 or the armature 618' of the bobbin magazine relay 618, until, of course, the holding circuit is broken.

From its junction with line 636, line 638 continues to the other armature of relay 632, namely armature 632''', which alternately connects into the circuit lines 640 and 642. When the relay is open, line 640 is energized, supplying current to one side of a single pole, double throw switch 108, which is the carriage reversing or direction limit switch. The other side of armature 632''' connects line 642 in series with line 638 when the relay is actuated, and line 642 in turn, connects with the other side of the single pole, double throw switch 108. Consequently, the line 644 on the output side of switch 108 can be placed in series with line 638 irrespective of whether relay 632 is actuated or not.

As just mentioned, switch 108 is the carriage direction limit switch that moves with the carriage and serves to reverse its direction when engaged by a limit stop adjacent each end of the track traversed by the carriage. In order for this switch to perform this function, the line 644 extends therefrom to the solenoid 646 of a solenoid-actuated 4-way valve 104. This valve, it will be recalled, controls the flow of compressed air to the air motor 96 driving the carriage, such connection being through the armature 618'' of the bobbin magazine relay 618 and a line 645. The valve 104 has a normal position to which it is biased when solenoid 646 is de-energized, so that unless otherwise controlled, the air motor will drive the carriage

in one given direction, say to the left. The direction limit switch, on the other hand, is both normally open and normally closed, remaining in one position until mechanically shifted to the other position by engagement with the corresponding limit stop.

Line 642 is also connected directly via a line 648 to the solenoid 144 which serves to actuate the carriage locking mechanism and is thus effective to maintain the carriage stationary in proper registration with a given spindle position, and by a line 650 to the solenoid 652 of the solenoid-actuated throttle valve 106 on the exhaust side of air motor 96. It will hence be seen that both of solenoids 144 and 652 will respond to closure of the carriage drive relay 632 when yarn sensing switch 380 is closed by the absence of yarn, assuming that the spindle position registration switch 132 and magazine relay armature 618 are so aligned as to complete the series connection to the yarn sensing switch.

It was perhaps observed as the description has proceeded that the operation of the present apparatus was referred to in terms of a cycle. In addition, reference was made to a control shaft 628 earlier in the discussion of the circuit diagram. It will be clear that once the yarn has been found missing at a given position and the carriage has become locked in proper place in registration with that position with an empty bobbin in readiness for delivery thereto, rotation of control shaft 628 is initiated to set into operation a control cycle regulating in proper timed relation all of the various functional mechanisms involved in restoring that position to productive conditions.

The control shaft is driven by a motor 660 to which current is initially fed from line 630 by a series of lines and switches, as follows. Line 654 branches from line 630 before the latter's connection with switch 624 and extends to a switch 664. This switch is connected by a short line 656 to another switch 666 which finally joins to motor 660 by a line 658. Both of switches 664 and 666 are mechanically actuated by cams rotating with control shaft 628. Moreover, both of these switches are of the single pole, double throw type and are normally biased to the downward position, as shown in the drawings. Switch 664 is referred to herein as the control motor switch while switch 666 is referred to as the vortex cycle switch. With both of these switches in the "closed" position shown, to complete the circuit to motor 660 through line 658, rotation of motor 660 is initiated.

Control shaft 628 has mounted thereon at various points of its length, a number of plate cams, some of which serve to actuate electrical switches, already referred to in part, and others of which effect direct actuation of valves for controlling the supply of compressed air to the various air cylinders mentioned in the course of the mechanical description. In view of the scale of the diagram of FIG. 30, no attempt has been made to represent the physical configuration of the cams with the actual cam surfaces in proper angular relationship necessary for carrying out the intended sequence of actions. Rather, a separate timing diagram is included as FIG. 31, showing the chronological relationship of the major functions under the control of the camshaft. It will be understood, however, that the cams are configured with projecting lobes and occasionally, notches, at the proper point thereon to which reference may be made during the description for convenience of expression. Specific values for the timing in terms of degrees of rotation will likewise be given, it being recognized, of course, that such values are for illustration only and are not necessarily critical.

Preparatory to beginning the manipulative functions of the cycle, the control shaft switch 664 is re-set. This switch opens at the very end of the cycle to disconnect motor 660, after the carriage drive relay 632 has been de-activated to put the carriage back in motion, leaving line 630 without current at that stage. When the carriage drive relay is reactivated at the next position to be serv-

iced, switch 664 passes current to motor 660 despite its "open" position so that motor 660 can be started and move switch 664 directly to closed position, connecting directly with main line 611. This movement is effected by cam 668 which throws switch 664 as soon as shaft 628 starts to rotate. With the carriage held in operative position by the relay 632, the first step is to retract the yarn sensing or feeler wire 376 to clear the area above the spindle position. This step is controlled by cam 672 which actuates an air valve 674 within the first 15 degrees of rotation. Next, the rotating spindle must be braked and by the time the control shaft has rotated 60 degrees, a control cam 676 has fully actuated an air valve 678 supplying the air cylinder projecting the spindle brake shoe into engagement with the spindle whorl. Coincidentally, the yarn thread eye retracting cylinder 346 is actuated by cam 680 opening an air valve 682 for supplying air to that cylinder.

The path is now clear for doffing the wound bobbin from, and for applying a new bobbin to, the spindle and it will be remembered that the bobbin transport arm has a normally inoperative position in registration with the spindle position when the carriage is itself properly registered. To depress the bobbin elevator rod for engagement with the wound bobbin, a cam 684 opens a valve 686 after 75° of rotation and at a few degrees later, say 15°, to allow the elevator rod time to complete its movement, the pneumatic bobbin clamp is actuated by a cam 688 opening a valve 690 to admit air to the expandable bellows and set the clamp. Rotation of the shaft another 15° closes the valve 686 again to allow the elevator rod to retract and after retraction is complete (another 15°), the bobbin transport arm is pivoted to align the elevator rod with the wound bobbin magazine entrance.

The air cylinder pivoting the bobbin transport arm derives its control from a cam 692 actuating a valve 694 regulating its supply of air. The high point of the cam 688 passes from under the handle of valve 690 at about the 120° point, opening the bobbin clamp to drop the wound bobbin into the magazine entrance and thence to the storage compartment for wound bobbins.

Preparation is preferably made for attaching the yarn to the bobbin. The vortex nozzle 486 (vortex II) must be positioned horizontally and vertically in that order, the former being controlled by a cam 696 opening a valve 698 by about the 136° point while the latter is controlled by a cam 700 opening a valve 702 by the 150° point, the valves 698 and 702 governing the admission of compressed air to the appropriate air cylinders. Coincidentally with the vertical positioning of vortex nozzle II, the empty bobbin detent is set to hold surplus empty bobbins within the magazine chute while the magazine gate is being operated. This is carried out by a cam 704 opening the control valve 706 to admit air to the detent air cylinder.

At this point, when the control motor 660 has turned the cam shaft a total of 150°, vortex cycle start switch 666 is thrown by a cam 670, cutting off the current from line 662 to temporarily halt rotation of the control motor and initiating the ring traveller threading phase of the cycle, during which phase the control shaft remains stationary (see note at top of FIG. 31). Before proceeding to a detailed description of this phase, a preliminary action should be mentioned. Branching off from line 630 after the latter's connection to carriage restart switch 624, is a line 710 which ultimately terminates at a solenoid 712 which controls a solenoid-actuated valve 714 for admitting air to the strand delivery suction vortex nozzle (vortex I), the other side of the solenoid extending back to main line L₂. Thus, the supply of air is initiated to vortex nozzle I, immediately upon energization of the carriage drive relay 632 and continues until that relay is opened.

When switch 666 is actuated by cam 670 to disconnect line 658 and the control motor 660, the switch is thrown into connection with line 716 which, at its other end, con-

ncts with one side of the lifter fork limit switch 452. Ganged with switch 452 is another switch 718 so that the two switches move in concert. Lifter fork limit switch 452 has a normal position indicated in solid lines in the diagram at whch it remains until mechanically thrown by the movement of the lifter fork as discussed in the course of the mechanical description. When in the solid line position and with current supplied to line 716 it connects to line 720 which leads to the sub-circuit regulating the movement of the strand threading vortex nozzle.

At its ultimate end, line 720 branches into a line 722 connected to one side of an armature 724' of a double armature relay 724, and into a line 726 connected to one side of the vortex I upper limit switch 338. When relay 724 is de-energized, armature 724' connects into the circuit a line 730 running to one side of motor 328 which drives the vortex nozzle positioning chain. The initial function of motor 328 is to elevate vortex nozzle I 288 from inoperative to operative position adjacent the nip of the draft rolls, and line 730 is so connected to the motor as to cause its rotation in the appropriate direction. Switch 338 is thrown from its normally open position when the vortex nozzle reaches the upper limit of its travel. Closure of this switch connects line 726 with a line 728 extending to the coil 724c of the relay, energizing that coil and moving the relay armatures from their normal solid line positions to the dotted line position of the drawings. Such movement disconnects armature 724' from line 730 and brings it into connection with a line 732, setting up a holding circuit for coil 724c. While motor 328 could be of the 3-phase type, special wiring not otherwise needed for the apparatus would then be needed. Preferably, therefore, motor 328 is a reversible single phase motor including the capacitor 736.

Relay 724 has a built-in time delay of a few seconds, and on actuation, its armature 724" is connected to a line 738 which extends to the other side of motor 328 to reverse the direction of motor rotation. During the period of the delay provided by relay 724, vortex nozzle I remains at the nip of the delivery draft rolls 38 to engage the drafted roving issuing therefrom and it will be recalled that a preferred feature of the invention is the provision of an oscillating or rocking motion for vortex nozzle I generally lengthwise of the delivery draft rolls in order to expand the strand locating capacity of the suction nozzle. The electric motor 364, for effecting such rocking movement, is connected to line 720 by a line 740 ending on one side of a switch 742 which is ganged with the vortex nozzle upper limit switch 338 so as to open and close in tandem with that switch and a line 744. Consequently, motor 364 cannot operate except when vortex nozzle I is in proper position proximate to the draft roll nip.

It will be further recalled that motor 364 along with the mechanical array for oscillating vortex nozzle I are mounted on a pneumatically propelled slide 352 projectable to and retractable from working position. Obviously, motor 364 should not operate until the slide is fully extended and for this purpose, the slide limit switch 363 is connected in series with switch 742 and the motor by the line 744. The movement of slide 352 is itself governed by a solenoid 741 connected to switch 742 by a line 743 and regulating a valve 745 governing the air supply to slide-positioning air cylinder 366.

Branching off from line 728 prior to its connection with relay coil 724c is a line 746 extending to the switch 336 which is the lower limit switch for vortex nozzle I. This switch is normally open and it is closed when the nozzle drive motor 328 has completely retracted the nozzle drive chain and nozzle. Closure of this switch, which indicates that the drafted strand has been taken by vortex nozzle I from the nip of the draft rolls and delivered downwardly along a path passing adjacent to the ring rail of the spinning frame and is in readiness for the remainder of the threading phase, is used to initiate a series of op-

erations. First, current is passed to a line 748 which connects with a solenoid 750 for actuating a valve 752 controlling the supply of compressed air to the pneumatic cylinder operating the threadder fork 392. Another line 5 754 is also connected into the circuit by closure of vortex I lower limit switch 336, this line extending to the thread fork limit switch 404 that is actuated when the threadder fork has reached its extreme inner position. Switch 404 is a normally open single pole, single throw switch and, 10 when closed, connects to a line 756 extending to the coil 760c of a double armature relay 760. This relay has a built-in time delay on actuation of a few seconds. One of its armatures 760' is connected, when the relay is de-energized, to a line 762 extending to a solenoid 764 for 15 actuating a valve 766 which controls the supply of compressed air to the air jet 420 acting to thread the strand on the traveller. Thus, after threadder fork limit switch 404 has closed, the delay in the energization of relay 760 will provide a brief period for the air jet to release a burst 20 of air to propel the traveller around the ring into engagement with the strand. Then, relay 760 closes, cutting line 762 out of the circuit to stop the flow of air through air jet 420.

Branching from the short line 656 between the two 25 cam disc controlled switches 664 and 666 is one end of a line 770 which connects at its other end to one side of the relay armature 760" of the threading jet relay 760, the other side of this armature being connected to a line 772. As switch 664, the control shaft switch, has continued 30 in closed position, closure of armature 760" brings about actuation of a solenoid 774 connected to line 772, by a branch line 775. Solenoid 774 actuates a valve 776 controlling the supply of air to a pneumatic cylinder for manipulating the thread lifter fork 436 which, it will be 35 recalled, lifts the strand from traveller engaging position to a position extending in chordal relationship to the ring 50, the final fraction of movement of this fork serving to close the thread shear blades to sever the chordally extending thread section from the length of yarn engaged 40 in the vortex nozzle I. Arrival of the lifter fork at its operative position but before actuation of the thread shear serves to open the lifter fork limit switch 452 mechanically and, as the normally open switch 718 is ganged with limit switch 452, switch 718 closes to establish a connection 45 between line 772 and line 656 by way of a line 780.

The opening of the lifter fork limit switch 452 disconnects all of the components utilized in connection with the positioning and actuation of the vortex nozzle I as well as of the threadder fork and threading jet, including the 50 relays 724 and 760. However, since closure of switch 718 re-establishes the connection from lines 656 to line 772, previously provided by line 770 and armature 760", compressed air continues to be supplied via valve 776 to the air cylinder positioning the thread lifter fork so that 55 this fork ultimately reaches its extreme position, resulting in closure of the thread shear and release of the thread from the influence of vortex nozzle I.

At this point, control over the operation is returned to 60 control shaft 628 which has continued in stationary position following disconnection of line 658 upon the actuation of switch 666 by cam 670. Control motor 660 is thus re-energized as a result of actuation of lifter fork limit switch 452 bringing into connection with line 716 a shunt line 782 extending to line 658 of the motor and shaft 628 resumes its rotation.

When the thread is released from the grip of the suction vortex nozzle I 288, it must be engaged immediately 65 by the vortex nozzle II 486. The latter nozzle is already situated in operative position and suction is already being maintained therein by virtue of certain preliminary operations heretofore described. Thus, as soon as the thread is severed by the shear blade, its free end is drawn down into the suction tube of vortex nozzle II and is ready for further manipulation.

75 The first development upon re-starting the control

motor is the provision of an empty bobbin in the magazine entrance for delivery to the bobbin transport mechanism. The magazine gate is accordingly now pivoted by its air cylinder, which is under the control of a valve 710, actuated by a cam 708 on the control shaft. Cam 708 is effective to fully open valve 710 after the shaft is rotated an additional 15° to the 165° point. A further projection on cam 684 opens the valve 686 to depress the elevator rod toward the empty bobbin waiting on the gate, the elevator rod being fully depressed as the shaft reaches the 180° point. Simultaneously, the operating lobe on the cam 700 passes out from under the operating lever, for valve 702, allowing that valve to close so that the air cylinder for positioning of suction nozzle II vertically returns to its lowermost, inoperative position, drawing the thread downward through the ring on the ring rail along a path generally adjacent the spindle post, this movement also being completed by the 180° point.

As soon as the elevator rod is fully depressed, the pneumatic clamp at its lower end is actuated by the arrival of a second operating surface on the cam 688 under the operating lever for valve 690, closing the clamp around the tip of the bobbin. Next, the elevator rod is returned to normal elevated position by the removal of the second lobe on cam 684 from operative position, which is followed by the removal of the salient on cam 692 from a position actuating valve 694, so that valve 694 closes and the bobbin transport arm returns to normal position with the elevator rod in axial alignment with the spindle post. The control shaft has now rotated a total of 225°, each of the steps just mentioned requiring a period of approximately 15° for completion. As the clamp continues to hold the bobbin by its tip, the elevator rod is once more depressed by the arrival to operative position of a third lobe on the cam 684, opening valve 686 for a last time to lower the elevator rod to place the empty bobbin onto the spindle post. The second lobe on the cam 688 now passes from operative position, opening the bobbin clamp to release the bobbin and the bobbin elevator rod returns to its elevated inoperative position as the last lobe thereon passes from operative position and the elevator rod control valve 694 closes.

The empty bobbin is now in position on the spindle post ready for engagement thereon of the strand. As the empty bobbin is being donned, the thread extends from the nip of the delivery pair 38 of draft rolls through the crotch of the up-ended guide eye 40, then essentially vertically downwardly to the traveller, and thence at a slight forward angle downwardly past the base of the spindle to a point just above the spindle whorl, at which point it is restrained by the action of vortex nozzle II. It may be remarked parenthetically that the vortex nozzle II continues to insert twist into the strand to maintain its structural integrity and to accommodate any surplus length of yarn provided by the delivery action of the draft rolls, such surplus length actually issuing out of the discharge end of the nozzle to spin harmlessly in mid-air. While lying in this path, the strand does not hinder the arrival of the empty bobbin nor become snagged on any part of the bobbin clamp.

Before the strand is engaged by the empty bobbin, the thread eye 40 is returned to operative position by the departure of the operative surface of its cam 680 from the position actuating valve 682 and the eye-positioner air cylinder returns to normal retracted position, flipping the thread eye downwardly to normal working position. Now, the cam 676 for the spindle brake moves away from valve 678 as the control shaft continues to rotate, closing valve 678 to allow the brake actuating cylinder to retract the brake shoe. Thus released, the spindle post and empty bobbin begin to rotate and the strand is engaged by the notch provided for that purpose in the base of the bobbin, wrapping itself about the bobbin, the length extending into vortex nozzle II backwinding onto the spindle beneath the bobbin.

The spindle position in question has now been restored to operation, the roving being spun normally thereon and collected onto the new take-up bobbin. Before returning the carriage to its controlling condition, however, it is preferred to obtain confirmation that the spindle position is performing normally, and in the event this is not the case, to render that position inactive to further response by the carriage, as well as to alert the machine attendant that some difficulty beyond the capacity of the apparatus to handle is present at this position. Although it would be within the scope of the invention to have the apparatus repeat the entire threading operation if it did not succeed in doing so on the first attempt, experience has indicated that in the great majority of cases, the apparatus will perform successfully on the first attempt if it is to perform successfully at all. In addition, repetition of the operating cycle would prolong the period of withdrawal of the carriage from its patrol and delay the speed with which the carriage gives service to the next spindle position.

Accordingly, the illustrative embodiment is equipped to test the results of the threading operation. This phase of the cycle is initiated by a switch 790 which is under the control of a cam 792. Switch 790 connects a line 794 branching off of line 614, extending directly from the yarn sensing switch 380, prior to its connection with spindle registration switch 132 with a line 796. So long as the yarn sensing switch is maintained in open (dotted line) position by the presence of the yarn when its supporting slide is projected back into operative position at approximately the 300-315° point, closure of yarn test switch 790 will connect line 796 into the circuit, resulting in the energization of solenoids 798 and 162, respectively. Solenoid 798 actuates an air valve 800 controlling the flow of compressed air to the air cylinder which operates the blade which severs the roving so that further delivery of the roving to the set of draft rolls will be ended to minimize the production of waste. The other solenoid, it will be recalled, projects the cam blade 164 which is effective to move the cover plate 156 for the spindle position to a location closing off the position registration notch associated with that position, preventing further actuation at such position of the spindle registration switch.

It is conceivable for the apparatus of the invention to become ineffective as a result of some radical failure, such as breakage of some component, loss of proper adjustment, or other unforeseeable defect, and preferably measures are taken to detect the occurrence of such a condition, referred to as carriage failure since the defect presumably originates in the carriage, and to bring about immediate cessation of operation. In general this is accomplished by pulsing a counter in response to the passage of current through the line 796, the counter being effective to abruptly stop the apparatus in mid-cycle when the total of such pulses reaches a predetermined number, unless a threading operation is successively completed in the meantime, in which event the counter is returned to zero.

In the working embodiment, the counter takes the form of a step relay referred to herein as the carriage failure step relay 810, arbitrarily selected to have a total of three steps, although any other number could be substituted if desired. The relay 810 is connected to line 796 by a line 812 extending to the coil 810c of the relay, the armature 810' being advanced one step on each occasion the line 812 receives current from line 796. The terminals contacted by the armature 810' in its starting position and each of the first two steps are connected in parallel to the line 814, extending to the control shaft motor to complete the circuit to the motor from side L₂. The third and final step of relay 810, on the other hand, has no such connection and, consequently, arrival of the armature at this step leaves the control motor without current so that it stops dead without completing the

operating cycle, all components remaining in the position occupied at the time including the carriage. To alert the operator to the occurrence of a carriage failure, the final step of the relay 810 is connected by a line 816 to a signal light 818.

In the event the present apparatus is unsuccessful in one or two attempts but is successful on or before the third attempt, step relay 810 is restored to starting position. To this end, the yarn sensing switch 380 in (yarn present) open position connects to a line 820 extending to one side of the second armature 632" of the carriage drive relay 632, which armature, when the relay was first energized by the closing of the yarn sensing switch, supplies current through a line 822 to a reset coil 810r of step relay 810. Energization of the reset coil restores the armature 810' to its normal or starting position shown in solid lines.

The step relay is reset also by the machine operator once the difficulty repeatedly preventing successful operation of the apparatus has been remedied. Thus, reset coil 810r is also adapted to be energized by the closure of a manual reset switch 824 through a line 826.

Although the machine attendant can visually observe the existence of de-activated spinning positions on the frames assigned to him, earlier attention will result if each frame is provided with a signal or indicator adapted to be actuated whenever the yarn test phase of the apparatus determines that any position cannot be successfully threaded. For this reason, a line 830 branches off from line 796, extending from the test switch 790, to connect with the coil 832c of a mechanical locking relay 832. Energization of coil 832c closes the relay armature 832' connecting into the circuit via a line 834 a frame failure signal lamp 833 to attract attention. Once closed, the armature 832' is mechanically locked in such position until the relay 832 is deliberately reset by energization of a reset coil 832r by a manual reset switch 838 via a line 840. Line 834 receives current independently from side L₂ when the armature 832' is closed and, consequently, the carriage failure signal lamp remains lighted until the lock relay is reset without regard to further manipulation of the yarn test switch 790, which remains closed only a brief period covering 315-320° of control shaft rotation.

As already indicated, carriage failure step relay 810 completes the circuit to control motor 660 by connecting that motor to the side L₂ through line 814 at all times except upon the accumulation of three successive failures in threading up three different positions, at which point the control motor is immediately cut off irrespective of the position assumed by the various control switches regulated from the control shaft 628. However, the other side of motor 660 remains in connection with side L₁ since the ganging of the switch 718 with the thread transfer fork limit switch 452 sets up what is, in a sense, a holding circuit for limit switch 452. To explain the latter statement, as long as control motor switch 664 is in its normally closed position, which is the case except during the period covering 357-360° of the cycle, line 656 will receive current as will line 780 connected to line 656, and the thread lifter fork will remain projected until the switch 718 is opened. However, the switch 718 cannot open until the lifter fork limit switch has been restored to starting position which cannot occur so long as the thread lifter fork remains in projected position. Necessarily, then, the limit switch remains closed to continue the connection of the control motor with side L₁. Therefore, unless prevented by the operation of step relay 810 as just explained, motor 660 will continue to rotate. In the meantime, cam 670 had closed the vortex cycle switch 666 at about the 300° point. Return of the vortex cycle switch does not affect the position of the thread lifter fork limit switch 452, however, which continues to be held by its "holding circuit."

Opening of carriage restart switch 624 initiates the final

major phase of the cycle, and occurring during approximately the period corresponding to 350-350 degrees of rotation of the control shaft 628.

The first incident to the opening of the switch 624 is the de-energization of carriage drive relay 632 which occurs by virtue of the disconnection by switch 624 of line 630, energizes the relay coil 632c, from the holding circuit constituted by that line together with lines 622, 634, 636, 638, and 611. Return of the relay to starting position also opens the throttle valve 106 on the air motor exhaust, restoring the motor to full operating speed, and simultaneously releases the carriage locking solenoid to permit the carriage to resume its patrolling activity in its original direction of travel. Finally, as has already been mentioned, the step relay reset coil 810r is energized to restore that relay to starting position if necessary.

Even though the carriage now resumes its patrolling activity, the cycle control shaft has not quite completed its entire cycle and shaft 628 continues to rotate. Carriage restart switch 624 now closes preparatory to participation in the next operating cycle as the shaft passes the 355° point.

Finally, after 357° of control shaft rotation, a notch on the cam 668 passes beneath the operating lever for the control shaft switch 664, opening that switch and thus disconnecting line 656 and control motor 660 from line 611 extending back to side L₁. The motor thus stops at substantially the 360° point. Incidental to the opening of the control shaft switch 664, the current to the solenoid 774 maintaining the thread lifter fork in projected position, is cut off, closing the valve 776 and allowing the fork positioning cylinder to return to normal position, retracting the fork. Departure of the latter from its projected position returns the thread lifter fork limit switch 452 to closed position in readiness for the initiation of the next cycle of the strand delivery vortex nozzle I.

It may be helpful to explain that connection of control motor switch 664 in series with carriage restart switch 624 (in closed position) does not result in current flowing to motor 660. Switch 624 is also in series with yarn sensing switch 380 and spindle position registration switch 132, which coincide in closed position only when yarn is absent from a position.

During the course of the explanation of the circuit diagram just concluded, an effort was made to explain the operation of the respective components as well as their relationship to the mechanical arrangement of the invention, with the exception of the manner in which the carriage drive is controlled and the latter will now be explained. It will be recalled that the carriage driving air motor 96 is solenoid actuated and the actuating solenoid 646 has a normal position such that the air motor control valve 104 causes the motor to drive in one direction which was assumed to be leftward. With the carriage drive relay 632 in normal de-energized condition to supply current to line 640, the air motor will drive the carriage to the right as long as the carriage direction limit switch 108 is in the solid line position in the drawing, energizing lines 644 and 645 and the control valve solenoid 646. However, as the switch 108 is shifted to the dotted line position as a result of engagement with the limit stop 109 at the right hand end of the frame, the solenoid will be de-energized and in returning to its normal inoperative position, will restore the air motor to its normal driving condition to the left.

The reversal of the carriage drive direction incidental to the initiation of the threading operation is accomplished in essence by reversing the polarity of the lines connected to the terminals of the carriage direction limit switch 108. Thus, when the carriage drive relay 632 is energized, closure of the armature 632" disconnects line 640 while connecting line 642. If the limit switch is positioned as shown in solid lines so that solenoid 646 is energized and the carriage is driving to the right, disconnection of lines 640 cuts off the current from solenoid

646 and the carriage drives to the left. On the other hand, if the limit switch is at the dotted line position so that the carriage is driving to the left (since armature 632" is open and line 642 receives no current), closure of the relay swings the armature 632"" into connection with line 642 supplying current through the limit switch to solenoid 652 to drive the air motor to the right.

When the last empty bobbin is removed from the magazine, switch 218 opens, releasing magazine relay 618 which opens armature 618" and deenergizes the direction limit solenoid 646. Consequently, the air motor will drive the carriage to the left end of the frame where the carriage will remain until a new supply of bobbins is placed in the magazine chute. The carriage direction limit switch under these circumstances is ineffective and the air motor will merely stall as the carriage is held at the end of the frame. The attendant can re-load the magazine and remove the wound bobbins or automatic means for doing so can be provided, once the carriage is locked in registration position, removal of the last empty bobbin does not result in return of the carriage to re-loading position until the machine cycle is complete.

In the foregoing description, unless otherwise indicated, all valves are 3-way valves, having an "on" position feeding compressed air to the air cylinder, for example, and an "off" position allowing the air to be exhausted from the cylinder. Similarly, all air cylinder are single acting and are biased to return to normal inoperative position unless otherwise indicated. Several variations and alternatives have been mentioned as the description has proceeded and those skilled in the art will appreciate that others could be made without departure from the spirit of the invention.

ALTERNATIVE EMBODIMENT

Apparatus for piecing-up separated yarn ends

As has already been indicated, the present invention may take the form including means for recovering the free end of yarn from the partially wound take-up package and manipulating that end for piecing-up of reunion with the free end from the roving. Such an alternative embodiment will now be described. The structure of this alternative embodiment is illustrated in FIGS. 33 through 50.

In connection with the description of this alternate embodiment, the details of the spinning frame, main carriage and main carriage drive mechanisms and certain of the other components of the main embodiment hereinbefore described have not been repeated. It will be understood that this alternative embodiment is adapted for use with a spinning frame, and will include the same carriage, carriage support, carriage drive means as set forth for the main embodiment. Furthermore, certain other elements and mechanisms of the main embodiment may be employed in this alternative embodiment and these will be noted in the ensuing description. In view of the fact that such elements and components have already been described in detail it will suffice, in certain instances, simply to include an appropriate identifying statement. In other instances, more detailed description has been repeated, notwithstanding that a full discussion of such component or components was presented earlier. This latter approach has been elected where something more than a mere reference back to the first embodiment was deemed of value to a full understanding of this alternate embodiment.

In any event, insofar as the parts of the principal embodiment are again repeated they will be identified by the reference numerals previously accorded the given parts in the earlier described embodiment. To the extent that parts of earlier described embodiment are shown and described in a modified form in this alternative embodiment the reference characters will be repeated herein with a prime affixed.

In general, this alternative embodiment includes means

75

for connecting or "piecing-up" the free yarn end attached to the partially wound take-up package with the free end from the roving and comprises the steps of halting rotation of the package having the broken yarn end thereon, retrieving the free outer yarn end from the package, threading the outer yarn end from the package through its traveller and then delivering this end to a knitter, retrieving the free end of roving, drawing the roving to said knitter while twisting the roving into yarn, operating the knitter to unite the newly spun yarn with the yarn end from the take-up bobbin, and finally reinitiating the winding and twisting cycle.

Referring now to FIGS. 33 and 34, there is generally illustrated the travelling main carriage C together with its corner posts 72 rigidly upstanding from the corners thereof. The carriage, its rails 74, 76, its motive power means, and its stopping means are identical with those described with reference to the first embodiment hereof. Also, the roving bobbin creel 28 and roving bobbin R are illustrated. The roving Y is illustrated in its usual path extending from its supply bobbin R and flowing through drafting rolls 36, 37 and 38, being directed in course of such flow by trumpet guide 39. Upon emergence from the drafting rolls the attenuated roving passes through the self-threading guide eye 40 supported on articulated bracket 42, and onto bobbin B supported on spindle 46 to wind take-up package P. As described earlier, each bobbin B is surrounded by a ring 50 carried on ring rail 52, the ring being provided with a traveller 54 which rides therearound. Thus, as rail 52 is reciprocated and the bobbins are driven, the roving is twisted in the zone below or downstream of the drafting rolls and distributed along the length of each take-up bobbin B.

As set forth with the first embodiment feeler wire 376 serves to sense the presence of yarn at each station and is adapted to close switch 389 to impart a signal in the absence of yarn. In this embodiment feeler wire 376 is carried on the end of piston 384 operated by cylinder 382. Piston 382 is operable to retract the feeler wire 376 from the piecing-up zone during the joining cycle, see FIG. 48. Furthermore, an elongated piston rod 344 is provided to abut against a finger 340 and rock yarn guide 40 upward (FIGS. 46, 47) when the piecing-up cycle is initiated thereby leaving the central zone clear of this instrumentality during rejoining of the strands.

It will, of course, be recognized that all of the description so far of this alternative embodiment has dealt with components already set forth in greater detail in connection with the main embodiment.

In this alternative embodiment it is necessary when "piecing-up," i.e., when repairing a break in the strand at any twisting position, that the strand end from the take-up bobbin be manipulated to a reuniting position to be joined with the roving end. For achieving this goal there is provided means for rotating the particular bobbin being serviced as it is raised or transported from its driving spindle during the piecing-up cycle. The purpose of such rotation will be a matter for subsequent discussion. Referring again to FIG. 33 there is provided an elevator rod 252', similar in function to its counterpart (elevator rod 252) of the main embodiment, but modified to the extent that it is rotatable. The lower end of elevator rod 252' carries the same cam-operated 3-jaw clamp 262 described in connection with the main embodiment. As earlier stated, this 3-jaw clamp 262 includes three levers 264, each having a jaw 266 at one end. Levers 264 are fulcrumed in a 3-legged bracket 268 fixed on the extreme lower end of rod 252'. The opposite ends of the levers 264 are inclined for engagement with the periphery of a conical actuating cam 270 slidably encircling rod 252' and which is coupled to the lower face of a pneumatically expandable bellows 272. The bellows 272 is of toroidal configuration so that the elevator rod 252' can pass through the central opening thereof, see FIG. 37. When compressed air is admitted to bellows

272, the actuating cam 270 is urged downwardly along rod 252', thereby rocking levers 264 about the arms of bracket 268 and, thus, bringing the jaws 266 to gripping position, all as explained in connection with the first embodiment.

Elevator rod 252' has already been described as rotatable. It is also to be noted that rod 252' is fixed against translation. To this end a heavy support bracket 880 is affixed rigidly to an upright corner post 72 of the carriage and extends outwardly therefrom toward the spinning machine. An extension bracket 882 is secured to the outer end of bracket 880. A compressed air cylinder 256' for operating elevator rod 252' vertically is connected onto bracket 882, the cylinder being directed upwardly from its position on said bracket. The upwardly projecting piston rod 258' of the cylinder 256' has a horizontal platform or deck 260' affixed to its outer terminus. Deck 260' has a motor mount 884 fastened thereto, the motor mount, in turn, providing support for an electric motor 886. The shaft of motor 886 mounts a bevel gear 888 thereon which mates with a further bevel gear 890 keyed to the upper end of elevator rod 252'.

In order that bellows 272 may be connected to a source of compressed air and, yet, may be rotatable there is provided structure including an external shaft 892 surrounding elevator rod 252' for substantially the entire length of the rod and supported for rotation in bearings 893, 893a. With particular reference now to FIG. 37 it will be seen that a clearance space is provided at 894 between elevator rod 252' and the internal wall of shaft 892, which said space affords a suitable passage for air to bellows 272. In turn, bellows 272 is tightly sealed to the lower end of shaft 892 and to the upper end of cam 270. The upper end of shaft 892 has a flare received within the confines of a nut 896. This nut 896 has an internal thread engaging a mating thread on a shank of a further nut 898. The shank of said nut 898 protrudes through a hole in deck 260' and the enlarged flange-like head 899 of nut 898 engages the top of deck 260'. Hence, as nuts 896, 898 are drawn together they lock tightly in position on deck 260'. Nut 898 has a centerless shank to provide an air passage at 900 communicating with air space 894. A gasket 902 is positioned between the upper end of nut 896 and the lower surface of deck 260' to seal against the passage of air therebetween. Additionally, the lower face of nut 898 and the upper face of the flare of external shaft 892 are machined smooth in order that air may flow between passage 900 and space 894 with minimum of loss at this interface.

A hollow cap 904 providing an air chamber 905 internally thereof is secured to the upper face of flange 899 by means such as welding to prevent escape of air from the chamber. The upper reach of cap 904 is formed as a threaded shank 906. A stop nut 908 engages 906 to secure suitable packing 909 in place between the rod 252' and the cap. Also, shank 906 is bored through to receive rod 252', the bore, in effect, forming a guideway to prevent deflection of the elevator rod. A connector 910 is seated in a suitable aperture through the sidewall of cap 904 and is connected to a source of compressed air. Thus, it will be seen that as air is admitted to chamber 905 it flows freely through passage 900 and space 894, entering and expanding bellows 272 to force actuating cam 270 downwardly along rod 252', rocking lever 264 about the arms of bracket 268 to bring jaws 266 to gripping position. Simultaneously with such action, elevator rod 252', the axis of which is aligned with bobbin B when in its operating position, is lowered toward the bobbin on the spindle so that the jaws may seize the top of the bobbin as they close. In this connection, cylinder 256', which controls the vertical movement of elevator rod 252', is preferably of the double-acting type to control the movement of the rod between fixed upper and lower limits. Furthermore, motor 886 is energized promptly after elevator rod 252' has seized bobbin B and released it from its drive spindle.

Consequently, elevator rod 252' and shaft 892, which is pinned to rod at 912, is driven to rotate the bobbin. The control means for the aforesaid three functions, i.e., operating rod 252', moving jaws 266, and rotating rod 252' will be described hereafter.

As bobbin B is lifted off its driving spindle and rotated, all in the manner just recited, mechanisms are operated to locate the free outer end of yarn on the bobbin, and to withdraw this end for eventual reuniting with its companion roving end running from the roving supply. To this end a stiff plate 920, see FIGS. 33, 34, 38 and 39, is pivotally supported on a post 922 which passes through one corner of the plate. The lower portion of post 922 is embedded in a pad 924 welded to upright member 72. Plate 920 acts as a base for a vertical rib 926 which is welded to said plate and extends upwardly therefrom. The uppermost end or rib 926 has a metal plate constituting a platform 928 to which an electrical motor 930 is anchored. A conventional speed reduction unit 932 is connected integrally with motor 930 and, in turn, a shaft 934 is engaged drivingly with said speed reduction unit. As a result, as motor 930 is energized shaft 934 will rotate somewhat slower than the motor shaft for purposes to be apparent shortly. Spaced bearings 936 are affixed to a side of rib 926 and provide a bearing support for shaft 934.

As seen in FIG. 34 the lower end of shaft 934 is provided with a suitable chuck or collet 938 which acts to hold the shank of a brush 940. Said brush 940 lies in a plane coinciding generally with and normally spaced away from the uppermost end of bobbin B as this bobbin rests on its driving spindle (see FIG. 33). As will be more fully described hereafter the brush 940 is operative to locate the outer end of yarn on the package P as part of the overall piecing-up cycle.

Brush 940 and its operating mechanism have now been described as pivotably supported on post 922 for movement in a horizontal plane. There is provided a pneumatic cylinder 942 for effecting this pivoting movement. Thus, cylinder 942 is supported below plate 920 with its rear terminus pivotably connected to a bracket 944 affixed to the frame of carriage C. A piston 946, working in cylinder 942, has its forwardmost end pivotally attached to the lower side of plate 920 by a link 948. Desirably, this link is positioned rather closely to post 922 thereby affording relatively rapid swinging of the plate 920 and brush 940 as the piston 946 extends. Hence, when compressed air is admitted to drive piston 946 out of cylinder 942, plate 920 is quickly pivoted from its inactive position to its active position. In this active position brush 940 is disposed in the vertical plane of movement of package P, as shown in FIGS. 34 and 38. It should here be indicated that during movement of plate 920 to its active position brush 940 is caused to rotate by controls yet to be described. Rotation of the brush desirably is in the same direction in which the bobbin is rotated as yarn is wound thereon during the normal winding cycle. Substantially simultaneously with arrival of brush 940 at its active position, package P is elevated and rotated in a sense opposite to that in which it was rotated as yarn was wound thereon. During doffing, the periphery of package P is moved against brush 940 and, hence, the package is swept by the brush. In the course of this scanning action the loose outer end of yarn Y' on the package is gathered into the bristles of the brush and a length of the outer yarn, thus, entwined in the bristles, is withdrawn from the package.

Once the outer yarn end Y' has been picked up from the package by brush 940, further steps are initiated to manipulate this end to a position for joining to its companion end from the roving. To this end, and referring to FIG. 34, a gusset or rib 949 is welded to plate 920. An electric motor 950 equipped with a conventional speed reducer 951 is mounted on said rib 949. A stub shaft 952 (FIGS. 38-40) projecting from the speed reducer 951 has

a capstan 954 carried thereon for rotation therewith. The capstan 954 is provided with an enlarged flange 955 forming a rear wall therefor. A plurality of radial projecting tines 956 are embedded in flange 955, these tines being positioned to intersect the bristles of brush 940 at right angles for purposes of wiping the yarn therefrom by an upward sweeping motion. A generally semicircular hood 958 is fixed in a position surrounding the major part of the circumference of capstan 954. A bracket 959 affords support for the hood 958. As seen in FIG. 40 hood 958 is disposed closely adjacent flange 955 and, as will be more fully explained hereafter, negative pressure is created in hood 958 to urge the yarn delivered thereto by tines 956 to wrap partially around capstan 954. By virtue of the fact that capstan 954 has its periphery covered with material such as rubber having a high coefficient of friction, coupled with the partial vacuum created in hood 958, the yarn engaged on the capstan and under the hood is unwound from bobbin preparatory to its reuniting with its companion roving end.

In FIGS. 33 through 36 there is illustrated an elongated cam track 970 which serves as a guideway for mechanism operating to remove the yarn from capstan 954, deliver the yarn for threading through its associated ring traveller, and thereafter convey the yarn to the knoter to be joined with its relating roving end. Cam track 970 includes an inclined upper end 970a connected to a bar 960 (FIG. 33) constituting a support portion of the frame of carriage C. The lower end of track 970 is also inclined as at 970b and is joined to a rib 963 which is also a part of the framework of carriage C. The central region of track 970 is an essentially vertical portion 970c.

With particular reference now to FIGS. 33 and 36 a plate 964 is provided which acts as a support for a cross-slide 966 having an elongated slot 967 therein. Cross-slide 966 serves as a mount for a suction transfer nozzle 968 communicable (FIG. 40) with the zone immediately below the forward end of hood 958. A suction hose 969 (FIGS. 34 and 36) is provided to connect suction transfer nozzle 968 to a suitable suction source. A pair of vertical guide stanchions 972, 973 project through suitable apertures in plate 964 and extend through slot 967. Said stanchions 972, 973 are suitably fastened at their uppermost ends to a support member 976 (FIGS. 33 and 34), which is, in turn, connected to carriage C. The lower ends of the stanchions are secured to deck 70 of carriage C. Thus, cross-slide 966 is positioned for sliding movement on the surface of plate 964 toward and away from bobbin B with the guide stanchions 972, 973 acting to prevent lateral sliding movement of the plate. A pair of studs 974 pass freely through slot 967 and are embedded in plate 964. These studs are employed to join cross-slide 966 with plate 964, the broad, flat heads of the studs loosely overlaying the side-walls of said slot 967. Cross-slide 966 has a roller 978 attached to one of its edges (see FIG. 33) and aligned to ride on a surface of cam track 970. A relatively heavy spring 980 is connected at one of its ends (left end in FIG. 36) to the bottom of cross-slide 966 at an edge remote from that carrying roller 978. The distal end (right end in FIGS. 35 and 36) of spring 980 is attached to plate 964. Hence, spring 980 functions to bias roller 978 into engagement with track 970. Therefore, it follows that vertical movement of plate 964 will cause roller 978 to follow the contour of cam track 970, the roller being biased against track 970 by spring 980. In consequent thereof, horizontal movement will be imparted to cross-slide 966 as the cross-slide moves generally vertically in the zones of portions 970a and 970b of the track.

A vertically arranged lead screw 990 acts to impart vertical movement to cross-slide 966. Said lead screw 990 is threadedly engaged (FIGS. 35 and 36) suitably secured, as by welding, to a feed nut 992 in plate 964. The lower end of the lead screw is coupled for rotation to a known type of reversible electric motor 994 through a conventional slip-clutch 996, the motor being suitably supported

on the carriage framework. The upper end of lead screw 990 is retained for rotation in a pedestal bearing 998 affixed to a cross arm 999 which is fastened to the support structure of carriage C. Thus, it will be appreciated that 5 motor 994 is operated in timed sequence to move the suction transfer nozzle 968 upwardly from its rest position (FIG. 34) to an operative position (FIG. 40) with its suction orifice closely adjacent hood 958 through steps next to be described.

With the yarn end held by nozzle 968 as seen in FIG. 36, motor 994 is energized to drop plate 964 to the lower extreme of lead screw 990 thereby orienting the yarn adjacent ring rail 52 as illustrated in FIG. 41. When the suction nozzle is at this lowermost position slip-clutch 996 functions to disengage the drive of motor 994 from lead screw 990. At this point the yarn end Y' is disposed in a generally vertical path proximate to its associated ring 50 and traveller 54. The threading steps are performed next and these are illustrated in detail in FIGS. 41 through 20 45. As in the case of the first embodiment hereof, the threading instrumentalities are mounted on vertically movable sub-carriage I. For a full description of this sub-carriage reference is made to the first embodiment hereof. At this point it will suffice to restate that the engagement of opposed guide rollers 128, 130 with rail 126 (all as shown in FIG. 2 and described in connection with the earlier embodiment), projecting from ring rail 52, causes the sub-carriage to move bodily with the ring rail. Thus, the relative position of all of the parts mounted on the sub-carriage I remain constant with respect to the ring rail, notwithstanding that the ring rail continues its traversing motion during the threading steps next to be described.

The instrumentalities for effecting threading-up of the yarn Y' with ring traveller 54 are substantially the same 35 as those described for the first embodiment. However, since the strand to be threaded in the traveller in the instant embodiment is the yarn end Y' from the take-up package P (as distinguished from the end R' from the roving which is threaded into the traveller in practice 40 with the first described embodiment) threading is effected therefore at the diametrically opposite side of the spindle from that set forth for the first embodiment.

With attention now to FIGS. 41 through 45 illustrating the threading steps of the instant embodiment in detail, the first step is to deflect the yarn Y' from the path assumed as it extends between package P and transfer nozzle 968 to a further position extending around a portion of the exterior ring periphery to permit engagement of traveller 54 therewith. It is not deemed necessary to repeat fully the description of the threading instrumentalities involved in effectuating threading of the traveller other than to state that these elements are generally the same as those described for achieving the same steps in connection with the first embodiment with the modifications specifically mentioned herein. It will be recalled that shelf 390, supported on sub-carriage I, serves as a mount for slidable threading fork 392. Fork 392 has a slot 394 extending through most of its length and terminating in a transverse extension 396'. Guide studs 398, passing through slot 394, control the path of movement of fork 392 and it will be observed in FIGS. 41 through 45 that a line passing through the mid-point of these studs extends to a point of tangency on ring 50 essentially diametrically opposite to that of the first embodiment. The forward end of fork 392 is notched at 400. The driving force for threading fork 392 is supplied by an air cylinder 406 having its rear end held in abutting relation to a brace 408 (see FIG. 45). The piston 410 of the cylinder has its free end affixed to a push block 412 joined to the outer end of fork 392 through a link 414.

Thus, movement of threading fork 392 inwardly from the rest position as shown in FIG. 41 to the advanced position of FIG. 42 will cause the notched end 400 of the fork to engage yarn Y'. Continued inward movement of threading fork 392 will deflect the yarn as illustrated in

sequential views, FIGS. 43 and 44, delivering the yarn to the left-hand side of package P as seen in the last mentioned views. Just before the fork is fully extended inwardly, the curved slot end portion 396' comes into engagement with the outermost of studs 398. This imparts to the notched end 400 of fork 392 an abrupt swinging movement rightwardly (FIG. 44) toward package P. The combined effect of this lateral and axial motion is to wrap the yarn Y' from the point of tangency with the ring periphery around a short arc of that periphery, rising over the rim of the ring flange to the crotch of notch 400 and then upwardly to package P as shown in FIG. 45.

With the yarn Y' in its deflected position as just described traveller 54 is propelled around its ring 50 (clockwise in FIGS. 41 through 44) by an air burst from jet 420 as earlier described. As a result, the yarn is engaged by the traveller and threaded therethrough. At this time fork 392 is retracted to its inoperative position clear of ring rail 52.

Once the threading procedure has been accomplished, 20 i.e., yarn Y' is re-engaged in traveller 54, motor 994 is reversed by electrical control means, to be described later, to rotate lead screw 990, driving suction transfer nozzle 968 and, hence, yarn end Y' upwardly to the upper limit of the lead screw where slip-clutch 996 is once again 25 operable to disconnect the driving force of motor 994 from lead screw 990. In this uppermost position the yarn end Y' is in position for entry into a conventional knotter 1000 (FIG. 35) where it eventually will be joined with its 30 associated roving end. For a more detailed description of the knotter, reference is made to U.S. Patents 672,636 of Apr. 23, 1901, and 755,110 of Mar. 24, 1904, both to H. D. Colman.

With particular reference now to FIGS. 34, 35 and 38 knotter 1000 is supported on a cross-slide 1002 carried on relatively heavy, rigid support bracket 1004, which is welded to the framework of carriage C. A yarn bail 1005 is fixed on knotter 1000 and projects forwardly therefrom. Viewing FIG. 34, cross-slide 1002 is provided with an elongated slot 1009. A pair of flat-headed studs 1010, 1011 are passed through slot 1009 with their ends secured at the underside of bracket 1004. Thus, cross-slide 1002 is moved along the surface of bracket 1004, the studs, while allowing free horizontal sliding movement of the cross-slide, serve to prevent lateral motion of the cross-slide.

The driving force for cross-slide 1002 and its associated knotter 1000 is supplied by an air cylinder 1012 (FIG. 38) which has its rear end fastened to a brace 1014 depending from the lower side of plate 1004. The piston rod 1016 has its free end affixed to a push block 1018 rigidly joined to the outer end of cross-slide 1002 through a link 1020. Thus, after a controlled time delay sufficient to permit transfer nozzle 968 to deliver yarn Y' to the just-described upper position, knotter 1000 is advanced from its rest position as seen in FIGS. 34 and 38 to its active knot-tying position as illustrated in FIG. 35, by piston rod 1016. Once knotter 1000 assumes its active position, motor 994 is once again reversed to lower transfer nozzle 968 to its rest position as shown in FIG. 35 somewhat below the plane of the knotter. A switch 1022 (FIGS. 33 and 35) is mounted on the frame of carriage C with the armature 1023 thereof (FIG. 33) extending to be contacted and depressed by roller 978 as nozzle 968 reaches its rest position. Depressing armature 1023 now stops motor 994. As transfer nozzle 968 descends, the yarn end Y' is caused to carry over bail 1005 and enter the knotter to be retained thereby, the various elements and the yarn now assuming the position as illustrated in FIG. 35. It will be seen in FIGS. 34 and 35 that an air cylinder 1024 is fixed in a transverse position on cross-slide 1002 and the free end of the piston rod 1026 of said cylinder is connected with a linkage 1028 for operating the knotter. Hence, when piston rod 1024 is extended, knotter 1000 is operated to tie a knot joining strands engaged therein.

The means for controlling the several steps just described will be set forth in detail hereafter.

In sequence, following the steps for placing the yarn end Y' in the knotter 1000 as just described, the roving end R' is next retrieved for delivery to the knotter. Thus, with reference to FIGS. 33 through 35, vortex suction nozzle I 288 (the details of construction and operation of which have already been set forth in describing nozzle 288 of the first-described embodiment) is connected to the free end of a piston 1040. The opposite end of the piston is contained within an air cylinder 1042 which is fastened on a horizontal bracket 1044 adapted for vertical movement along a member 1046. In turn, member 1046 is connected to the frame of carriage C by struts or braces 1048. A vertically directed air cylinder 1050 is arranged adjacent member 1046, the rear end of the cylinder being affixed to an angular bracket 1052 welded or bolted to said member 1046. The piston rod 1054 of cylinder 1050 is disposed for downward vertical motion and carries on its outer, free end a link 1056 which is attached to one side of a slider 1058. The opposing side of slider 1058 is suitably formed to extend through and be guided in an elongated slotted track 1060. The interior portion of slider 1058, i.e., that portion extending through the slot of track 1060 is connected to horizontal bracket 1044.

From what has been said, it will be seen that vortex nozzle 288 will be moved inwardly to the nip of the delivery rolls to retrieve the loose roving end R' issuing therefrom once transfer nozzle 968 has stopped at its rest position. This motion is, of course, obtained by admission of air to cylinder 1042, this cylinder during this procedure being in its uppermost position (as shown in solid lines in FIG. 35) by virtue of the vertically arranged piston rod 1054 being in its retracted position. Once vortex nozzle 288 has advanced to seize the roving R' it is retracted by operation of piston rod 1040 being withdrawn into its cylinder 1042. As has already been fully explained when setting forth the operation of vortex nozzle 288 in the earlier embodiment, the nozzle is operable in response to vortical air flow within the nozzle to impart to the roving R' twist such that it is formed into a yarn as it is manipulated by the nozzle. Advantageously, the yarn is twisted by the vortex nozzle I 288 in the same direction in which the yarn is twisted in normal operation of the machine. Here again, as with the earlier described embodiment, the rate of movement of vortex nozzle 288 cannot exceed the delivery rate of the draft rolls if the strand is to remain intact and, preferably, the rate of movement of the vortex nozzle with the strand therein is slightly less than that of the draft rolls. The vortex nozzle copes with any excessive strand length created thereby in accordance with the procedure set forth with the principal embodiment. The movements just described are controlled by means yet to be set forth in detail.

In timed sequence after the strand R' has been extended by vortex nozzle 288, i.e., when piston 1040 is retracted within cylinder 1042 (see FIG. 35), air is admitted to cylinder 1050 to move nozzle 288, and hence strand R', downwardly. In the course of this descending movement the strand R' is laid across the tying portion of knotter 1000 juxtaposed to yarn end Y', as illustrated by the broken lines in FIG. 35. Here again, the rate of movement of the strand R' is controlled so as not to exceed the delivery rate of the draft rolls. Such movement is controlled by regulating the admission of air to cylinder 1050. At this point strands Y' and R' are threaded in knotter 1000. Control means yet to be described are operated next to admit air to cylinder 1024 thereby operating knotter 1000 and reuniting the roving end R' with the strand end from package P. Simultaneously therewith the spindle brake 172 (described in connection with first embodiment) is released, thus freeing the spindle for further rotation. Vortex nozzle 288' is returned to its

uppermost position by operation of air cylinder 1050 after a time delay sufficient to permit operation of the knotted 1000. In view of the fact that the knotted acts in a fraction of a second to tie the yarn, the yarn is released therefrom during acceleration of the spindle. Consequently, the yarn is pulled over bail 1005 and into the V-notch of guide 40 and the normal spinning cycle is once again under way.

FIG. 49 is a block diagram schematically showing the electro-mechanical control system of this alternate embodiment. An explanation of this diagram will now be presented. Preliminary thereto, it should be pointed out that for ease of illustration the connector lines to the E.M.F. source have not been shown in the circuitry. Rather, these connectors are merely indicated by an arrow head, it being understood that the components so indicated would be connected into the power supply for energization therefrom.

There is provided a main control shaft 628' (there being a similar shaft 628 described in connection with the first embodiment herein) which has mounted thereon at various points along its length a number of plate cams, some of which operate switches, and others of which control valves regulating the supply of compressed air to the air cylinders referenced in the course of the mechanical description. No attempt has been made to represent the physical configuration of the cams with the actual cam surfaces in correct angular relationship required for carrying out the intended sequence of actions. Instead, a separate timing diagram is presented as FIG. 50, showing the timing relationships of the major functions under the control of the cam shaft. It will be understood, however, that the cams are configured with projecting lobes and, occasionally, notches at the proper positions on each of the cams to which reference may be made for convenience of expression during this description. Specific values for the timing in terms of degrees of rotation will likewise be given, it being recognized, of course, that such values are for illustration only and are not necessarily critical.

Control shaft 628' constitutes a portion of a conventional single cycle multi-cam timer of the general type, for example, sold by the Industrial Timer Corporation, Parsippany, N.J., as "Series RC Single Cycle Multi-Cam Timer." A principal feature of such a timer is, of course, that the control shaft makes one full revolution and stops.

In the diagram of FIG. 49 control shaft 628' is seen to be driven by a motor 1100 through a one-revolution clutch 1102. A suitable power source such as an E.M.F. source of 115 volts 60 cycles (not shown) is provided to operate the clutch and motor. A line 1104 is connected to the power source and is tied in to one side of the normally closed spindle position registration switch 132, fully described in reference to the first embodiment. This switch 132 is generally maintained in an open position by engagement with notches of the guide rail all as fully explained in reference to the first described embodiment. When closed, switch 132 connects line 1104 with a line 1106 connected to the opposite side of switch 132 and extending to one side of switch 380. This latter switch, it will be recalled, is actuated by yarn sensing feeler wire 376. This switch is of the normally closed type and is held open by tension in the yarn when yarn is present at each spindle position, the switch closing when such yarn at a position is absent. When closed, switch 380 connects with a line 1108 extending to conventional switch means (not illustrated) operable to pulse clutch 1102 and release the pawl means (not shown) normally locking the clutch against rotation. A further lead 1110 is connected from line 1104, to a switch 1111 of the clutch and a connector 1112 extends from this switch to the motor to insure a continued source of power to motor 1100 to achieve one full revolution of shaft 628' even in the event either of the switches 132 or 380 might open

prior to completion of a piecing-up cycle and thereby breaking the circuit through line 1108.

Thus, assuming that the carriage in the course of its patrolling has encountered a position where an end is "down," i.e., where there is an absence of a strand, the switches 132, 380 close as illustrated in FIG. 49. With continuing reference to this view, power is then passed to release the clutch and energize the motor whereupon shaft 628' is rotated through one revolution. It has already been described in connection with the first embodiment that in bringing the carriage to a halt in alignment with the spindle position to be serviced it is desirable to arrest movement of the carriage gradually. This, as also earlier mentioned, includes reversal of the carriage to return it to registration with the proper spindle position. Such action is achieved by reversal of the air motor driving the carriage. It will serve to repeat here by way of review that reversal of air motor 96 through operation of reversing switch 108 controlling a solenoid-operated 4-way control valve 104. Valve 104 supplies air to one side of the air motor to drive the carriage in one direction when the solenoid is energized. Similarly air is supplied to the opposite side of the motor to rotate it in the opposite direction when the solenoid is de-energized. Referring again to FIG. 49, the air motor is schematically illustrated as operably joined with the solenoid-operated 4-way control valve 104' through conduit 1114. Solenoid valve 104, in turn has current supply thereto through SPDT reversing switch 108, this switch being more fully described earlier. The opposite side of switch 108 is connected via line 1116 to one contact of a mechanically actuated single pole-double throw switch 1118. A line 1120 is connected to the opposite contact of switch 1118 and connects this switch with reversing switch 108. Line 1120 is connected with solenoid 144 of locking pin 148 through a further line 1122 for energizing said solenoid when switches 132 and 380 are closed.

From the foregoing it will be seen that in normal operation, i.e., when the carriage C is patrolling and in the absence of yarn breaks, current flows through switch 1118, line 1116, and switch 108 to energize solenoid valve 104 and direct air to one side of air motor 96 to drive the carriage in one direction. At the end of its stroke in a given direction the carriage is reversed by opening switch 108. This de-energizes solenoid valve 104 so that the valve returns to its normal position to which it is biased when de-energized. In consequence thereof the motor 96 is reversed in direction. At the opposite end of its run the air motor is again reversed by closing switch 108, thereby energizing solenoid valve 104.

Now, let it be assumed that a yarn break is detected by sensing wire 376. Control shaft 628' is rotated by means of clutch 1102 and motor 1100. After a relatively short period of rotation (about 6°) thereof a cam 1124 on shaft 628', operating through a suitable mechanical connection with switch 1118, throws this switch out of contact with line 1116 and into contact with line 1120. This step is effective to reverse air motor 96 since, obviously, if the current was, at the moment just prior to operation of switch 1118, flowing into solenoid valve 104 the valve will be deenergized. If, on the other hand, the solenoid valve was in its de-energized position, it will be energized by current flowing through line 1120 and switch 108. Simultaneously with the reversal of air motor 96, solenoid 144 is energized via lines 1122, 1120 to activate locking pin 148. As the carriage reverses locking pin 148 engages its appropriate notch in rail 76 to align the carriage with the position to be serviced. The solenoid 144 remains energized through approximately 330° of rotation of control shaft 628' to firmly hold the carriage on station during the piecing-up cycle.

Once the carriage is locked in position, preferably the first step is to clear the yarn sensing wire 376 from the piecing-up zone. This is achieved in substantially the same manner as described when discussing the first em-

bodiment. That is to say, after generally 30° of rotation of shaft 628' a cam 1126 affixed thereon throws a switch 1128 which, in turn, energizes the solenoid of a valve 1130 opening this valve to supply air to cylinder 382, the piston 384 of which carries wire 376. Consequently the wire is retracted from its operative position and so held until control shaft 628' has rotated approximately 300° whereupon the solenoid valve 1130 is de-energized to return the wire 376 to its operative position.

In the discussion of the embodiment first presented herein shunt mechanism is described which is operative to shunt the carriage registration mechanism around positions which are in a condition which is beyond the capacity of the apparatus to correct. In view of the fact that the energizing circuit for the shunt means is tied in with the over-all carriage signalling system it will be appropriate to discuss the circuitry for the shunt at this time. Since the shunt mechanism has been presented in detail earlier, and since the same shunt mechanism is contemplated for this embodiment, it will suffice to simply refer back to that description for the particulars thereof. It should be noted, however, that the operating means for the shunt mechanism of the instant embodiment is an air cylinder 1132 mounted on the inside of guide post 112 below locking pin guide block 150 on a bracket 1134. A solenoid valve 1136, controlling air flow to cylinder 1132 is connected via line 1138 to a SPST normally closed switch 1140. The contact of switch 1140 is connected to line 1108 via line 1142. In operation, switch 1140 is closed through a mechanical connection to a control cam 1144 on control shaft 628' after this shaft has rotated about 306° and is maintained closed through the ensuing 18° of rotation of the shaft. When shaft 628' has rotated about 324° cam 1144 operates through the mechanical connection to open switch 1140. If the apparatus has failed to piece-up the yarn (and such piecing should be completed when shaft 628' has rotated 305°) the position is shunted as described earlier. Thereafter, as the carriage again patrols past the shunted position the requisite signal needed to stop the carriage is not transmitted.

Reverting again to the operative motion attendant to the initial piecing-up procedure, preferably after approximately 30° of rotation of control shaft 628 the centering eye 40 is removed from the piecing-up zone. This step is controlled by a cam 1146 which actuates a switch 1148 to energize a solenoid valve 1150, thereby actuating the air cylinder 346 to lift eye 40 as explained in connection with the first embodiment thereof. The solenoid of valve 1150 stays energized until the doffing and donning phase of bobbin B is completed (such completion occurring after 150° rotation of shaft 628') whereupon switch 1148 is operated to cut air off from cylinder 346 to allow the cylinder piston to retract the eye 40 to return to its operative position.

As seen from the timing diagram of FIG. 50, spindle 46 is braked by the time control shaft 628' has rotated 30° and the brake is held on the spindle until about 282° of rotation of the control shaft. For this action a cam 1152 on the control shaft actuates a switch 1154 powering a solenoid valve 1156 to supply air to the air cylinder 1158 for thrusting brake shoe 172 into engagement with spindle 46. The brake is, of course, released when the air is cut off from cylinder 1158 by de-energization of solenoid valve 1156.

At this time the path is now clear to doff, i.e., lift the partially wound bobbin, seek the outer end thereon and withdraw that end off the bobbin, and eventually don the bobbin on its spindle. These steps are achieved by depressing elevator rod 252 and such motion is initiated after generally 30° rotation of control shaft 628'. A cam 1160 acts to throw a switch 1162 energizing a four-way solenoid valve 1164 to supply air cylinder 256', causing the cylinder piston 258', and rod 252', to move downwardly. During this downward motion (which continues from about 30° to 48° of the rotation of shaft 628') and after

some 42° of rotation of the shaft a switch 1166 under the control of a cam 1168 is actuated to energize a solenoid valve 1170 admitting air to expand bellows 272. Thus, the jaws or levers 264 are set clamping the bobbin.

It will be recalled that cylinder 256' has been described previously as of the double acting type. Four-way solenoid valve 1164, is thus de-energized after essentially 48° rotation of the control shaft to effect passage of air to the opposite side of piston 258', thereby driving this piston, the associated elevator rod 252', and the bobbin upwardly at a controlled rate of speed which, desirably, is somewhat slower than their speed of descent.

Coincident with the ascending of the bobbin, instrumentalities are operated leading to retrieval of the outer 15 yarn end from the bobbin. The controls for each is as follows.

Positioning of mounting plate 920 is governed by a cam 1172 on the control shaft which operates a switch 1174 connected to a solenoid valve 1176. In turn, the 20 solenoid valve 1176 regulates the admission of air to cylinder 942. Hence, when control shaft 628' has rotated about 42° switch 1174 is thrown by cam 1172, thus energizing solenoid valve 1176 to permit passage of air to cylinder 942. Consequently, piston 946 is extended to 25 pivot plate 920 to an operative position. In this position brush 940 is interposed in the vertical path of the ascending bobbin B. Also, capstan 95 is ready to receive the yarn end. Furthermore, the lower end of hood 958 is proximate to the open, forward end of nozzle 968 as 30 shown in FIG. 40, it being recalled that the rest position for the nozzle is in the plane of the hood and capstan 954. The mounting plate is held in this operative position for generally the next 48° of rotation of the control shaft.

At this point, i.e., with plate 920 operatively positioned, 35 and after generally 48° of rotation of control shaft 628', motors 886, 930 and 950 are energized. Thus, a cam 1178 on the control shaft actuates a switch 1180 powering motor 950 to rotate the capstan 954 in the direction of the arrow thereon in FIG. 40. Similarly as with the starting 40 means for motor 950, further cams 1182, 1184 activate respective switches 1186, 1188 to start motors 886 and 930, respectively. As already mentioned, motor 886 rotates bobbin B and motor 930 drives brush 940. In consequence thereof, brush 940 rotates against the periphery of the bobbin, lifting the yarn end therefrom. The 45 end becomes entwined in the bristles of the brush. Tines 956 sweep the yarn end from the bristles and draw this end over the surface of the rotating capstan 954. After generally 90° of control shaft rotation cam 1178 opens switch 1180 to deenergize motor 950 thereby stopping the 50 capstan. Likewise, motor 886 is stopped after about 102° of rotation of shaft 628' and motor 930 is halted after 90° of rotation of the control shaft, both actions, of course being controlled by the respective governing cams.

Simultaneously with the rotation of the capstan, bobbin and brush, just described, a negative pressure is introduced to transfer nozzle 968. Thus, a cam 1190 on shaft 628' operates a switch 1192 which, when closed, energizes a solenoid valve 1194 to connect the transfer nozzle 65 to the suction source via hose 969. As is apparent from FIG. 36 this suction source opens to transfer nozzle 968 until cam shaft 628' has rotated about 300° at which time the suction is shut off by virtue of cam 1190 opening switch 1192. In consequence of the suction through nozzle 968, the yarn is drawn into the nozzle and retained therein 70 by the suction. After generally 90° rotation of the cam shaft 628' plate 920 is retracted, i.e., it is swung counter-clockwise from the position shown in FIG. 38 to the position shown in FIG. 39, as air is exhausted from cylinder 942. Hence, capstan 954 is swung from beneath the 75 yarn Y', leaving the yarn extending in a straightline generally horizontal path between suction nozzle 968 and bobbin B, as shown generally in FIG. 36. At this time motor 994 is energized to position yarn Y' for threading into traveller 54.

The means for controlling the operation of motor 994 includes three cams 1196, 1198, and 1200 mounted on cam shaft 628'. A normally closed switch 1202 connected with motor 994 across line 1204, and held open by cam 1196, is released to close when cam shaft 628' has rotated 90°. As a result, connection is established between the power source and motor 994 via line 1203 and across one side of reversing capacitor 1204 to thereby energize the motor. Said motor operates in the first instance to turn lead screw 990 in a direction to move plate 964 and its companion cross-slide 966 downwardly. By virtue thereof, the yarn engaged in nozzle 968 is pulled downward. Thus, when nozzle 968 is in its lowermost position the yarn end from bobbin B extends downwardly in a line somewhat forward of spindle 46 as illustrated in FIGS. 41 through 45. Lead screw 990 is rotated in the direction to move cross-slide 966 downwardly under the control of cam 1196. When the cam shaft 628' has rotated approximately 108° the cross-slide is at its lowermost position. As has already been explained, motor 994 is provided with a slip-clutch 996 connecting it to the lead screw. Hence, the motor can be permitted to run while the cross-slide and associated suction nozzle are maintained in their lowermost positions and the slip-clutch will disengage the drive from the lead screw. By this means, the suction nozzle is held at its lowered position until cam shaft 628' has rotated about 144°. This delay involves several seconds during which interval the traveller is threaded.

As has been explained earlier, the traveller 54 is threaded by the actions of threading fork 392. Operation of this fork is initiated by a cam 1206 on the common cam shaft 628'. This cam 1206 is configured to open a normally closed switch 1208 to energize a solenoid valve 1210 when the cam shaft has rotated about 108°. As a result air is admitted to cylinder 406 to draw piston 410 into the cylinder thereby moving the threading fork 392 inwardly toward traveller 54, the fork performing its operative strokes to engage and present the yarn to the traveller ring 50 as illustrated in FIGS. 41 through 45. The energization of solenoid valve 1210 is maintained until cam shaft 628' has rotated 120°, at which time cam 1206 releases switch 1208 permitting it to close, thereby de-energizing solenoid valve 1210 and closing the air supply to cylinder 406. Thereupon, threader fork 392 is returned to its inactive position by conventional means acting within cylinder 406 to extend piston 410 and move the threader fork away from the spindle.

It will be appreciated that after the arrival of threader fork proximate to traveller ring 50 with the yarn engaged therein as illustrated in FIGS. 44 and 45 the fork is delayed momentarily prior to its retraction. During this delay a burst of air is expelled through jet 420 to propel the traveller 54 around ring 50 and into engagement with the yarn. Such action is controlled by a switch 1212 under the control of a cam 1214 on cam shaft 628'. Switch 1212 is connected to a solenoid valve 1216 which, in turn, controls the flow of compressed air to jet 420. Hence, upon generally 114° of rotation of cam shaft 628' (at which time the threader fork has moved inwardly with yarn Y' to the position of FIGS. 44 and 45) solenoid valve 1216 is actuated whereupon a burst of air is expelled through jet 420 to propel the traveller 54 and engage it with the yarn as previously described. This burst need only be for a brief duration. Therefore, cam 1214 operates after 120° rotation of the main cam shaft to de-energize solenoid valve 1216, consequently closing the air to the jet.

With the traveller threaded preferably the next step is to transfer the yarn end to region of knotter 1000. Control of this operation is from cam 1198. Thus, upon 144° rotation of cam shaft 628' cam 1198 is rotated from a location where it has previously held a normally open switch 1218 in a closed position to a further location where switch 1218 is permitted to open. Switch 1218 is connected to the opposite side of reversing capacitor 1204 from line 1203 via a line 1220. From capacitor 1204 line 75

1220 is connected with motor 994. Thus, the E.M.F. developed across capacitor 1204 induces a phase shift whereby motor 994 is driven in the opposite direction to that which it had in lowering suction nozzle 968. Consequently, the suction nozzle is elevated to the top of lead screw 990 where it is held momentarily. The slip clutch connecting the motor drive to lead screw 990 permits the motor 994 to continue to rotate during this interval without damage. As will be apparent from the timing chart of FIG. 50 motor 994 is energized in a direction to elevate the suction nozzle until cam shaft 628' has rotated about 180°. Obviously, the suction nozzle will have arrived at its uppermost position prior to said 180° of rotation of the cam shaft, say, after cam shaft rotation of about 165°. However, such timing is not critical to the operation of the unit so long as the suction nozzle is positioned above the knotter in advance of movement of said knotter.

Viewing the timing chart of FIG. 50 once again, preferably knotter 1000 is moved horizontally to its operative position as illustrated in FIG. 35 upon 180° rotation of cam shaft 628'. The horizontal positioning of the knotter is under the control of cam 1222 which actuates switch 1224 to energize a solenoid valve 1226. Energization of solenoid valve 1226 connects cylinder 1012 to the compressed air source whereupon knotter 1000 is projected into the path of the yarn end Y'. The knotter 1000 is held in this projected, operative position until the cam shaft has rotated generally 300° whereupon cam 1222 closes switch 1224 to shut the air supply to cylinder 1012.

The positioning of yarn end Y' in the knotter is controlled by the further cam 1200 on the cam shaft which, upon approximately 192° rotation of the cam shaft, allows a switch 1228 to close. This switch is connected to line 1203 via line 1230 and through normally closed limit switch 1022. Hence, with switch 1228 closed, current is fed through lines 1230 and 1203, through the opposite side of capacitor 1204 to that whereby motor 994 was reversed to drive the suction nozzle 968 upward. Therefore, the suction nozzle is once again moved downwardly until plate 964 opens switch 1022 to break the current flow to the motor. In the course of this motion the yarn end Y' is laid into the knotter, it being recalled that track 970 functions to cam the nozzle laterally in this upper zone adjacent the knotter. At this point the yarn Y' will have assumed the disposition as illustrated in FIG. 35.

Preferably as soon as suction nozzle 968 is stopped in its descent by the opening of limit switch 1022, i.e., upon 228° of rotation of cam shaft 628', vortex nozzle 288 is operated to manipulate air spun yarn R' to the knotter. Thus, air is simultaneously admitted to the vortex nozzle and to air cylinder 1042 so that the air spinning action of the nozzle is operating as the nozzle advances to seize the roving. A pair of cams 1232, 1234, operative to control respective associated switches 1236, 1238, are carried on the cam shaft. Cam 1232 operates to close switch 1236 upon 228° of rotation of the cam shaft and allows this switch to remain closed for the ensuing 72°, i.e., until the cam shaft has rotated 300°. With switch 1236 closed a solenoid-operated air valve 1240 connected therewith is energized, admitting air to the vortex nozzle.

At the same time that switch 1236 closes, switch 1238 is also permitted to close by its control cam 1234 thereby energizing a further four-way solenoid-actuated air valve 1242 to admit pressurized air to cylinder 1042. In consequence thereof piston 1040 is extended out of the cylinder to project the vortex nozzle forward to retrieve spun or twisted material R'.

The retrieval of material R' is completed by the time cam shaft 628' has rotated 240° and valve 1246 is de-energized at this time by the operation of cam 1234 opening switch 1238. On the return stroke the movement of piston 1040 is throttled down by a restrictive air orifice of the conventional four-way valve 1242. Hence, the rate of withdrawal of the roving is controlled so that the twisted material does not separate. When cam shaft 628'

has rotated about 270° vortex nozzle 288 is fully retracted toward cylinder 1042.

The next step involves dropping the vortex nozzle 288 vertically to present the spun or twisted roving into knotter 1000. To this end a cam 1244 on the main cam shaft controls a normally closed switch 1246 so that the switch is permitted to close upon 282° of rotation of the cam shaft. With switch 1146 closed a solenoid valve 1248 is energized to admit compressed air to cylinder 1050 as a result of which the cylinder piston 1054 is extended outwardly of the cylinder and downwardly as arranged herein. Again, the descent of piston 1054 is controlled via an air passage in the conventional solenoid valve so that the rate of descent of the vortex nozzle 288' and associated roving does not exceed the rate of issue of the roving from the drafting rolls. Of course, the yarn is also being continually twisted by means of the vortex nozzle as it is lowered to spin it into a yarn. At approximately 288° of cam shaft rotation the yarn R' is laid in the knotter (which is in the path of movement of the material R') adjacent the yarn end Y'. Thereupon, cylinder 1024 is charged with pressurized air to fire the knotter and join the two yarn ends.

Air to this latter cylinder is under the control of a cam 1250 on the cam shaft which is operative to control the opening and closing of a switch 1252 connected to a solenoid-actuated air valve 1254. As already indicated, solenoid valve 1254 is energized by the actuation of normally closed switch 1252 when the cam shaft has moved 288°. The firing of knotter 1000 is quite instantaneous and once the yarn is knitted the reunited yarn is dropped from the knotter to return to its normal thread-line for twisting and winding. The switch 1252 is actuated by cam 1250 at 294° to close off the air supply to cylinder 1024 whereupon its piston retracts, and in doing so recocks the knotter. As already explained, the spindle brake is preferably released at 282° of revolution of the cam shaft. The 6° interval between release of the brake and knotting (representing a fraction of a second) is desirable to place the yarn in the knotter under tension during the knotting operation and, also, to insure immediate winding thereof when knotting is completed.

At 330° rotation of the cam shaft the carriage motor is once again started by the operation of cam 1124. In the interval after knotting and prior to starting the air motor to resume patrolling of the unit the sensor shunt is operated in the manner already explained to close off the position from further attempts to piece-up the yarn and roving if the initial attempt has failed.

In the foregoing description the solenoid valves, unless otherwise indicated, are all conventional three-way valves having an "on" position feeding compressed air to the associated air cylinder, and an "off" position allowing the air to exhaust from the cylinder. Also, all air cylinders, unless otherwise indicated, are single acting conventional air cylinders and are biased to return to normal inoperative position.

Since certain changes may be made in the above-described apparatus without departing from the scope of the invention herein, it is intended that the foregoing description and accompanying drawings shall be interpreted as illustrative only and not in the limiting sense.

What is claimed is:

1. An assembly comprising a track, a carriage, means mounting said carriage for movement relative to said track, a connector, a line secured to said connector and to said carriage, and means for handling said line with

said line having a portion lying along said track, and including line receiving means receiving said portion of said line and opposed to said portion and said track.

2. An assembly as set forth in claim 1 in which said connector is substantially stationary relative to said track, the handling means mounts said line receiving means for movement along said track responsive to said movement of said carriage, and said portion of said line extends between said line receiving means and said connector and said portion is substantially free of relative movement during said movement of said carriage.

3. An assembly as set forth in claim 1 in which the handling means includes tensioning means for maintaining said line taut.

4. An assembly as set forth in claim 1 in which said line receiving means comprises a pulley wheel, and the handling means mounts said wheel for movement along said track with said line positioned for moving said wheel along said track in one direction responsive to movement of said carriage in one direction relative to said track, and said handling means includes a cable connecting said carriage and said wheel for movement of said wheel in a second direction along said track responsive to movement of said carriage in a second direction relative to said track, and tensioning means for maintaining said cable and said line taut.

5. An assembly as set forth in claim 1 in which the handling means mounts said line receiving means for movement in a path along said track, and the carriage mounting means mounts said carriage for said movement relative to said track along a path removed from said path of said line receiving means.

6. An assembly as set forth in claim 5 in which said paths are generally parallel and the path of said carriage is above the path of said line receiving means.

7. An assembly as set forth in claim 1 in which said connector is substantially stationary relative to said track, said line receiving means comprises a pulley wheel, the handling means mounts said wheel for movement in a path along said track with said line positioned for moving said wheel along said track in one direction responsive to movement of said carriage in one direction relative to said track, and said handling means includes a cable connecting said carriage and said wheel for movement of said wheel in a second direction along said track responsive to movement of said carriage in a second direction relative to said track, the carriage mounting means mounts said carriage for said movement relative to said track along a path generally parallel to and transversely removed from said path of said wheel, and tensioning means for maintaining said cable and said line taut.

8. An assembly as set forth in claim 7 in which the path of said carriage is above the path of said wheel, and said portion of said line extends between the line receiving means and said connector and is substantially free of relative movement during said movement of said carriage.
